Martin Press, Englewood, and Joseph Murgio, Clifton, N.J., assignors to International Telephone and Telegraph Corporation, Nutley, N.J., a corporation of Maryland

Filed Nov. 16, 1959, Ser. No. 853,121

10 Claims. (Cl. 235—150.27)

This invention relates to systems for determining and producing signals representative of the attitude, velocity and position of a vehicle in an imaginary given frame of reference, and particularly to such systems using rotation and translation sensors and determining the attitude, velocity and position of a vehicle with respect to earth latitude, longitude and altitude.

In the control and guidance of many vehicles, such as airplanes, missiles, artificial satellites, etc., it is important to determine the attitude or orientation and location of the vehicle with respect to a three-dimensional frame of reference, which frame may be fixed or rotating or translating. One use for such information is in enabling an airplane or missile to maintain its proper orientation and navigate in said reference frame either by pilot or human control or automatically. Another typical example of this is, of course, in inertial guidance systems, wherein, to determine velocity and position of the vehicle in a given reference frame, translational accelerations must be resolved in accordance with the attitude of the vehicle within said frame.

It has heretofore been proposed in inertial guidance systems for aircraft and missiles to employ a platform on which inertia sensors are mounted, the platform being maintained stable with respect to a fixed reference frame or with respect to a reference frame using the earth's vertical as one of its axes and latitude and longitude as its other axes. Such systems employ the inertia sensors to derive accelerations, velocities and translations of the aircraft or missile in the directions of earth latitude, longitude and gravity. To maintain such a platform orientated in the directions of latitude, longitude and gravity has required a complex structure utilizing a number of gyros and gimbals, one mounted upon another, driving servos, with inertia sensors feeding analog information to latitude, longitude and altitude computers which energize motors for maintaining the platform properly directed. Such stabilized platform systems are mechanically complex and present many difficulties both in manufacture and use.

Other inertial guidance systems do not employ a gimbal platform but rather continually compute the cosine of the angles between each axis of a craft or body and the axes and the reference frame. These cosines describe the position of a stable platform relative to the axes of the craft and are employed to modify the outputs from accelerometers fixed to the body axes to yield body acceleration in the directions of the axes of the reference frame. One example of such an inertial guidance system for computing cosines rather than employing a platform is described in the patent application by G. Deschamps, Serial No. 736,439, filed May 14, 1958, now Patent No. 3,176,119. The system described in the G. Deschamps application is sometimes called the "no-gimbal attitude computer" since it does not employ a gimbal platform.

For some applications of the "no-gimbal attitude computer," it is desired that the axes of the imaginary reference frame be at all times in the directions of latitude, longitude and gravity. If this is desired, it is necessary that the reference frame be rotated continually to account for the earth's rotational motion and the motions of the body relative to the earth.

Therefore it is an object of the present invention to pro-

2

vide means for rotating the reference frame in a "no-gimbal attitude and position computer" to align the reference frame axis with earth latitude, longitude and gravity.

It is another object of the present invention to provide an improved system for determining and producing signals representing the attitude, and velocity with respect to an orthogonal coordinate system with its axes oriented east-west, north-south, and vertical, and position of a craft with respect to earth latitude, longitude and altitude.

Another object of the present invention is the provision of such a system in which the stabilized platform is dispensed with and in which information as to the attitude of the craft is stored in a suitable storage device, and this attitude information is employed in conjunction with translational information from inertia sensors to continuously store information representative of the velocity with respect to an orthogonal coordinate system with its axes oriented east-west, north-south, and vertical, and position of the craft in terms of latitude, longitude and altitude.

In accordance with a main feature of the present invention, there is provided a system for providing information representing the attitude, velocity and position of a body with respect to an imaginary reference frame which is rotated to align with earth latitude, longitude and gravity, comprising means for sensing rotations and translations of said body, means coupled to said sensing means for producing signals representative of said rotations and translations, means for storing information representative of the attitude and velocity with respect to an orthogonal coordinate system with its axes oriented east-west, north-south, and vertical, and position of said body in terms of latitude, longitude and altitude and means coupled to said sensing means and said storing means for changing the information in said storage means to thereby continuously provide stored information representative of the position of said body in terms of latitude, longitude and altitude.

In accordance with another more specific feature of the present invention, gyroscopes and accelerometers are arranged with respect to the body, for example by being mechanically fixed thereto, so that the rotation-sensing axes of said gyros bear a fixed relationship to the orientation of said accelerometers whereby, as the vehicle rotates and accelerates with respect to the reference frame, signals representing these rotations and accelerations are produced, these signals being fed to computers which compute the body attitude and velocity with respect to an orthogonal coordinate system with its axes oriented east-west, north-south, and vertical, and position of the craft in terms of latitude, longitude and altitude and stores this information.

In accordance with a further feature of the present invention, the outputs from the gyros and accelerometers are quantized, each signal representing predetermined increments of body rotation and velocity and these incremental signals are used to vary the stored information.

Other and further objects and features of the present invention will become apparent, and the foregoing will be better understood with reference to the following description of embodiments thereof, reference being had to the drawings, in which:

FIG. 1 illustrates a spatial orientation of a body with respect to a reference frame;

FIG. 2 is a chart showing the interrelationship between stored numbers representing attitude of said body as controlled by gyro signals;

FIG. 3 is a diagram showing the general method of computing and storing matrix numbers representing attitude as controlled by gyro signals;

FIG. 4 is a diagram showing the general method for altering stored matrix numbers to account for rotations of the reference frame axes;

FIG. 5 illustrates the spatial orientation of reference frame axes relative to earth latitude, longitude and gravity;

FIGS. 6a, 6b and 6c are diagrams showing the general method of employing the outputs of inertia sensors fixed to said body and stored matrix numbers to compute body velocities in the direction of reference frame axes and for computing body latitude, longitude and altitude to yield signals representing increments of reference frame rotation about the reference frame axes;

FIG. 7 shows a partially pictorial view and block diagram of a gyroscope device for providing pulse signals each indicative of a given incremental angle of rotation of said body and providing a signal indicative of the sense of said rotation;

FIG. 8 shows a partially pictorial view and block diagram of an accelerometer device for providing pulse signals each indicative of a given increment of velocity of said body and providing a signal indicative of the sense of said increment and associated buffer circuits;

FIGS. 9a, 9b and 9c show diagrams and waveforms from which an understanding of the operation of a typical dynamic logic circuit may be had;

FIGS. 10a, 10b and 10c represent block diagrams of a matrix number computer employing dynamic logic circuitry for computing nine numbers representing the attitude of said body by the general method shown in FIGS. 3 and 4;

FIGS. 11a, 11b, 12a, 12b and 13 represent block diagrams of velocity and position computers employing outputs from said matrix computer for computing numbers representing latitude, longitude and altitude of said body by the general method shown in FIG. 6a;

FIG. 14 is a block diagram of dynamic logic circuits for performing the functions of the resolver device shown in FIG. 6b;

FIG. 15 is a block diagram of dynamic logic circuits for performing the functions of the ϕ and θ computers shown in FIG. 6b;

FIG. 16 is a block diagram of dynamic logic circuits for performing the functions of the δ_I and δ_{III} computer shown in FIG. 6c;

FIG. 17 is a block diagram of dynamic logic circuits for producing and buffering δ_{II} pulses thereby performing the function of increment detector 78 in FIG. 6a;

FIG. 18 depicts waveforms generated by an electronic clock and buffer circuits and employed in the dynamic logic circuits of FIGS. 11 through 17;

FIG. 19 depicts waveforms of fill-in pulses generated by said clock and shows the effect of shifting and filling in a serial binary number as accomplished by a typical dynamic fill-in circuit such as employed in FIGS. 11 through 17; and

FIGS. 20a, 20b, and 20c are block diagrams depicting the structure and operation of the electronic clock.

Turning first to FIG. 1, there is shown a spatial diagram from which an understanding of the theory of the no-gimbal attitude computer may be had. A body, such as a missile or an aircraft, 1 is shown having axes x, y, and z rigidly fixed thereto and extending from the origin 0 of sphere 2, which is preferably the center of gravity of the body 1, to the surface of sphere 2. Assume that body 1 rotates in three-dimensional space at an angular rate having components in the x, y, and z directions of ω_x , ω_y , ω_z . Furthermore, let the angular rate ω be represented by a vector $\bar{\omega}$ extending from the origin of sphere 2, its line of direction intercepting the surface of sphere 2 at point 3 which is the center of a circle drawn on the surface of sphere 2 and passing through some point P whose location on the surface of sphere 2 relative to the origin 0, may be represented by unit vector $\bar{R}$. Obviously, the instantaneous translational velocity of point P on the surface of sphere 2 may be represented by the vector cross product $\bar{\omega} \times \bar{R}$ as follows:

$$(A) \quad \bar{V} = \bar{\omega} \times \bar{R}$$

Since $\bar{\omega}$ may be represented by its components in the directions x, y, and z, namely, ω_x , ω_y , ω_z , and since $\bar{R}$ may be represented by its components in the directions x, y, and z, namely R_x , R_y , and R_z , the vector cross product may be written as follows:

$$(B) \quad \bar{V} = (\omega_y R_z - \omega_z R_y) i + (\omega_z R_x - \omega_x R_z) j + (\omega_x R_y - \omega_y R_x) k$$

In matrix notation the above expanded cross product may be represented by a matrix multiplication as follows:

$$(C) \quad \begin{bmatrix} V_x \\ V_y \\ V_z \end{bmatrix} = \begin{bmatrix} 0 - \omega_z \omega_x \\ \omega_z 0 - \omega_y \\ -\omega_y \omega_x 0 \end{bmatrix} \begin{bmatrix} R_x \\ R_y \\ R_z \end{bmatrix}$$

and the rotation rate matrix may be simplified for expression by the following identity:

$$(D) \quad [\omega] = \begin{bmatrix} 0 - \omega_z \omega_y \\ \omega_z 0 - \omega_x \\ -\omega_y \omega_x 0 \end{bmatrix}$$

Referring again to FIG. 1, we will now express the velocity of point P in terms of components along axes I, II, and III of a reference frame which is fixed in space and does not rotate as body 1 rotates. Obviously, this may be accomplished by expressing rotational vector $\bar{\omega}$ in terms of rotational components about axes I, II, and III and expressing vector $\bar{R}$ in terms of its projections along axes I, II, and III to yield a matrix equation for the velocity of point P in terms of its components in the directions of axes I, II, and III, denoted V_I , V_{II} , and V_{III} having the same form as the matrix equation, C, above. However, this obvious method will not be employed in this invention, but rather, another method will be employed whereby the matrix $[\omega]$ expressing the rotational rate of point P about axes x, y, and z will be retained. This is necessary because in practice the rotation rates ω_x , ω_y , and ω_z are readily available as the outputs from gyroscope rotation sensors fixed to the body 1 and oriented along the lines of axes x, y, and z of body 1, as shown in FIG. 1a. In order to employ the $[\omega]$ matrix, each of the components R_x , R_y , and R_z must be expressed in terms of their projections on axes I, II, and III to yield the following matrix equation expressing the projections of each of the velocity vectors V_x , V_y , and V_z on the axes I, II, and III:

$$(E) \quad \begin{bmatrix} V_{I_x} V_{II_x} V_{III_x} \\ V_{I_y} V_{II_y} V_{III_y} \\ V_{I_z} V_{II_z} V_{III_z} \end{bmatrix} = [\omega] \begin{bmatrix} R_{I_x} R_{II_x} R_{III_x} \\ R_{I_y} R_{II_y} R_{III_y} \\ R_{I_z} R_{II_z} R_{III_z} \end{bmatrix}$$

The above matrix equation may be written in another algorithm form for convenience of discussion as follows:

$$(F) \quad R = [\omega] R$$

The above algorithm form of the matrix equation may be put in incremental form by rewriting it as the following approximation:

$$(G) \quad \Delta R / \Delta t = [\omega] R$$

and since $[\omega] \Delta t$ is equivalent to δ which is the matrix form representing an increment of angle made by the path of point P on the surface of sphere 2 as subtended from the origin 0 during the interval Δt , the above may be expressed as follows:

$$(H) \quad \Delta R = [\delta] R$$

Since the matrix δ may be taken similar to the matrix $[\omega]$ to a first approximation it follows:

$$(I) \quad [\delta] = \begin{bmatrix} 0 \delta_z - \delta_y \\ -\delta_z 0 \delta_x \\ \delta_y - \delta_x 0 \end{bmatrix}$$

Another more accurate version of the δ matrix which reduces truncation error is as follows:

$$[\delta] = \begin{bmatrix} -\frac{(\delta_x)^2}{2}\delta_z - \delta_y \\ \delta_z - \frac{(\delta_x)^2}{2}\delta_x \\ \delta_y - \delta_z - \frac{(\delta_x)^2}{2} \end{bmatrix}$$

The truncation error exists because the interval Δt is finite and during that interval a rotation of body 1 about, say for example the x axis, will cause a third order change in the value of the projection of the vector $\mathbf{R}$ on the x axis, denoted herein as R_x , and, thus, a third order change in the value of the projection of R_x on the reference axes I, II and III, denoted herein as R_{Ix} , R_{IIX} and R_{IIIx} , respectively. Obviously, even more accurate matrices for δ could be employed in place of the approximate matrix shown in Equation I or in place of the third order correction matrix shown directly above, however, in order to simplify the embodiment of this invention herein described, which is adequate for most applications, use of the simpler matrix shown in Equation I will be disclosed in detail.

Referring again to Equation H, an algorithm equation for ΔR may be written in matrix form as follows:

$$(J) \quad \begin{bmatrix} \Delta R_{Ix} \Delta R_{IIX} \Delta R_{IIIx} \\ \Delta R_{Iy} \Delta R_{IIX} \Delta R_{IIIy} \\ \Delta R_{Iz} \Delta R_{IIX} \Delta R_{IIIz} \end{bmatrix} = [\delta] \begin{bmatrix} R_{Ix} R_{IIX} R_{IIIx} \\ R_{Iy} R_{IIX} R_{IIIy} \\ R_{Iz} R_{IIX} R_{IIIz} \end{bmatrix}$$

Next, performing the matrix multiplication on the right-hand side of matrix Equation J, the following nine simultaneous equations, one for each ΔR_{ij} are obtained:

$$(K) \quad \begin{aligned} \Delta R_{Ix} &= \delta_y R_{Iz} - \delta_z R_{Iy} \\ \Delta R_{IIX} &= \delta_y R_{IIz} - \delta_z R_{Iy} \\ \Delta R_{IIIx} &= \delta_y R_{IIIz} - \delta_z R_{Iy} \\ \Delta R_{Iy} &= \delta_z R_{Ix} - \delta_x R_{Iz} \\ \Delta R_{IIXy} &= \delta_z R_{IIXx} - \delta_x R_{IIXz} \\ \Delta R_{IIIxy} &= \delta_z R_{IIIx} - \delta_x R_{IIIz} \\ \Delta R_{Iz} &= \delta_x R_{Ix} - \delta_y R_{Iy} \\ \Delta R_{IIz} &= \delta_x R_{IIXy} - \delta_y R_{IIXz} \\ \Delta R_{IIIz} &= \delta_x R_{IIIxy} - \delta_y R_{IIIx} \end{aligned}$$

In order to simplify expressions, hereinafter let the subscript "i" refer to numerals I, II, and III and let the subscript "j" refer to letters x , y and z .

If each value of R at an instant of time t may be expressed by matrix $[R_{ij}]_t$, then matrix $[R_{ij}]_{t+1}$ is expressed as follows:

$$(L) \quad (R_{ij})_{t+1} = (R_{ij})_t + (\Delta R_{ij})_{t+1}$$

Each value of R at the time $t+1$, denoted generally as $[R_{ij}]_{t+1}$, may be expressed by one of the following nine simultaneous equations:

$$(M) \quad \begin{aligned} (R_{Ix})_{t+1} &= (R_{Ix})_t + (\Delta R_{Ix})_{t+1} \\ (R_{IIX})_{t+1} &= (R_{IIX})_t + (\Delta R_{IIX})_{t+1} \\ (R_{IIIx})_{t+1} &= (R_{IIIx})_t + (\Delta R_{IIIx})_{t+1} \\ (R_{Iy})_{t+1} &= (R_{Iy})_t + (\Delta R_{Iy})_{t+1} \\ (R_{IIXy})_{t+1} &= (R_{IIXy})_t + (\Delta R_{IIXy})_{t+1} \\ (R_{IIIxy})_{t+1} &= (R_{IIIxy})_t + (\Delta R_{IIIxy})_{t+1} \\ (R_{Iz})_{t+1} &= (R_{Iz})_t + (\Delta R_{Iz})_{t+1} \\ (R_{IIz})_{t+1} &= (R_{IIz})_t + (\Delta R_{IIz})_{t+1} \\ (R_{IIIz})_{t+1} &= (R_{IIIz})_t + (\Delta R_{IIIz})_{t+1} \end{aligned}$$

The typical numbers R_{ij} expressed in Equations M are represented as binary numbers in the no-gimbal computer. Thus, nine such numbers are represented in the computer in binary form and gyroscope device signals δ_x , δ_y , and δ_z from gyroscope devices represent equal increments of angles of rotation of body 1 about its axes x , y and z (see FIG. 1). These increments are chosen to be a power of 2 so that multiplication of R_{ij} by δ_x , δ_y , or δ_z , shown in Equations K, becomes a shifting process to shift each value of R_{ij} a number of places determined by said power

when multiplied by a δ_j pulse from a gyroscope device. In the embodiment of this invention herein described, a single δ_j pulse from a gyroscope device has been chosen for purposes of illustration to indicate a rotational angle of 2^{-6} radians. Obviously, system accuracy can be improved by decreasing the angle represented by a single δ pulse; for example, each pulse might represent a rotation of body 1 about one of its axes of 2^{-13} radians.

The effect of a δ pulse representing an increment of rotation of the x , y , or z axes upon the nine numbers R_{ij} expressed in Equations M is charted in FIG. 2. It will be seen from the chart that a δ_x pulse will produce no change in the numbers R_{Ix} , R_{IIX} , R_{IIIx} . It will further be seen that, there is a subtraction from R_{Iy} of a weighted portion of the value of R_{Ix} . The same pulse will cause an addition to R_{Ix} which is equal to the same fraction of R_{Iy} . Further inspection of the chart in FIG. 2 will show that for the same δ_x pulse, there is a similar subtraction from R_{IIX} and R_{IIIy} and a similar addition to the R_{IIz} and R_{IIIz} . For a δ_y pulse, representing an increment of rotation around the y axes, there is a similar process of addition and subtraction occurring between R_{Ix} and R_{Iz} , and R_{IIX} and R_{IIz} and R_{IIIx} and R_{IIIz} and for a δ_z pulse, there is a similar subtraction and addition between the numbers having x and y subscripts as likewise shown in the chart.

In the above chart, it is presupposed that the increments of rotation, that is, the δ_x , δ_y and δ_z are positive. If they are negative, the signs inside the boxes are reversed. After the computer for carrying out the functions indicated in the chart, FIG. 2, has been initially aligned, the successive δ pulses will change the numbers R_{ij} in the computer in accordance with the rotation of the x , y , and z axes so that the nine numbers will continuously represent the attitude of the x , y , and z axes with respect to the reference frame I, II, and III axes (see FIG. 1).

Generally, the no-gimbal or matrix computer will perform the operations of FIG. 2 by apparatus which performs the functions indicated in FIG. 3. Referring now to FIG. 3, each one of the nine numbers, R_{ij} , may be stored numbers in a separate register designated as 4 to 12, respectively. These may be in binary form and the registers may be, for example, either magnetic drums, pulse recirculating storage registers, etc. Since the circuitry connecting registers 4, 5, and 6 is the same as that connecting 7, 8, and 9, or 10, 11, and 12, a brief description of the circuitry connecting registers 4, 5, and 6 will suffice. When a δ_j pulse arrives accompanied by its associated σ_j signal which indicates the sign of the δ_j pulse, and said σ_j signal indicates positive, there is an addition made to one of the registers and a subtraction from another of the registers. This addition and subtracting may of course be reversed if said σ_j signal indicates negative. Such additions and subtractions to the number in each register 4, 5, and 6 are made by devices 13 to 18, each of which is designated "subtract" or "add" to indicate its function in response to the δ_j pulse controlling it, when that δ_j pulse is positive as indicated by its associated σ_j signal. The inputs to devices 13 to 18, which are indicative of the numbers to be added or subtracted to registers 4, 5, or 6, are obtained from weighting devices 19, 20, and 21 coupled to registers 4, 5, and 6, respectively. The function of each of these weighting devices is to read the number in the register to which it is coupled without altering said number and to weight the read number by effectively multiplying it by a factor equivalent to the value of a single δ_j pulse. For example, in each δ_j pulse may represent a rotation of body 1 about one of its axes of 2^{-6} radians and the numbers in registers 4 to 12 represented in serial binary form by 16 binary bits, the least significant bit first and the last bit representing the sign of the number; thus, the action of each of weighting devices 19, 20, and 21 is to alter the significance of each binary bit by reducing its significance six binary places. In other words, a negative number is

in a register represented in binary notation, least significant bit first, as 1010110010110011 would be weighted as 0010110011.

With the above being understood, it can readily be seen how the system of FIG. 3 operates in accordance with the chart of FIG. 2 when a δ_j pulse is received. The δ_j pulses and σ_j signals are derived from three gyroscope devices, such as shown in FIG. 8, each consisting of a single degree of freedom gyroscope, sensitive to rotations of body 1 about a different one of its axes x , y , and z . Assuming for the moment that a positive δ_x pulse is received from the gyroscope device responsive to rotations of body 1 about its x axis, this will actuate the "subtract" device 16 and the "add" device 18 feeding registers 5 and 6. A weighted portion of the coefficient R_{Iz} in register 6 will be subtracted from the coefficient R_{Iy} in register 5 while at the same time, the same δ_x pulse will actuate device 18 causing a weighted portion of R_{Iy} in register 5 to be added to the coefficient R_{Ix} in register 6. It will be seen that this corresponds to the operations indicated by the chart in FIG. 2. The same actions, in response to a δ_x pulse, will occur between registers 8 and 9 and 11 and 12, thereby changing the value of their corresponding coefficients. For a δ_y pulse, the "add" and "subtract" devices 14 and 17 will operate in accordance with the indication of FIG. 2, and for δ_z pulse, devices 13 and 15 will operate in accordance with the corresponding indications of FIG. 2. The additions and subtractions produced by the δ pulses in registers 4, 5, and 6, as hereinabove described, will also occur in registers 7 through 12 in a similar manner as indicated in the chart of FIG. 2. Therefore, assuming that the registers are initially aligned so that the numbers R_{ij} properly represent the orientation of the body axes x , y , and z with respect to the reference frame axes I, II and III, thereafter, as rotations of the body about axes x , y , z occur, the registers will change as heretofore indicated and continue to show the orientation of the x , y , and z body axes with respect to the reference frame axes. The nine outputs from the general matrix computer system shown in FIG. 3 are the nine weighted or incremental numbers ΔR_{ij} which are fed to a velocity and position computer.

In certain applications the reference frame axes I, II and III are rotated to maintain them aligned with earth longitude, latitude and gravity, respectively. Consequently, the coefficients R_{ij} are altered to, at all times, represent the angles between the body axis and the reference frame axis. The present invention features a method of accomplishing this. For an understanding of the method of rotating reference frame axes employed in the present application, reference is first made to FIG. 1 and Equations K. As previously described, Equations K represent changes in each of the coefficients R_{ij} as functions of increments of rotation of body 1 about its axes x , y and z and other of the coefficients. Furthermore, these Equations K are developed upon the presumption that the reference frame axes I, II and III remain rotationally fixed in space. Similar expressions to Equations K for representing changes in the coefficients R_{ij} can be formed as functions of increments of rotation of the reference frame about its axes I, II and III. These similar expressions are based upon the assumption that the body axes x , y and z are fixed in space. For example, if for the moment body axes x , y and z are assumed to be fixed in space and it is desired to rotate the reference frame about its axes I, II and III, by rotational increments δ_I , δ_{II} , δ_{III} , respectively, it is apparent by the same reasoning employed to form Equations K that the typical coefficients R_{ij} will be altered by an amount ΔR_{ij} expressed in the following nine equations:

$$(N) \quad \begin{aligned} \Delta R'_{Ix} &= 0 - \delta_{III} \cdot R_{Iix} + \delta_I \cdot R_{IIIx} \\ \Delta R'_{Iy} &= \delta_{III} \cdot R_{Iiy} + 0 - \delta_I \cdot R_{IIy} \\ \Delta R'_{Iz} &= -\delta_{II} \cdot R_{Ix} + \delta_I \cdot R_{Iix} + 0 \\ \Delta R'_{Iy} &= 0 - \delta_{III} \cdot R_{Iiy} + \delta_I \cdot R_{IIIy} \end{aligned}$$

$$\begin{aligned} \Delta R'_{Iy} &= \delta_{III} \cdot R_{Iy} + 0 - \delta_I \cdot R_{IIIy} \\ \Delta R'_{IIy} &= -\delta_{II} \cdot R_{Iy} + \delta_I \cdot R_{IIy} + 0 \\ \Delta R'_{Iz} &= 0 - \delta_{III} \cdot R_{Ix} + \delta_I \cdot R_{IIIx} \\ \Delta R'_{Iz} &= \delta_{III} \cdot R_{Ix} + 0 - \delta_I \cdot R_{IIIx} \\ \Delta R'_{IIIz} &= -\delta_{II} \cdot R_{Ix} + \delta_I \cdot R_{IIx} + 0 \end{aligned}$$

Upon comparing Equations N with Equations K, it is apparent that the axes x , y and z have been re-designated as axes I, II and III, respectively and vice versa. This is exactly what is physically intended by rotating the reference frame while maintaining the body fixed.

Turning next to FIG. 4 there is shown a method for altering the numbers R_{Ix} , R_{Iy} and R_{Ix} stored in registers 4, 5 and 6 of FIG. 3 to account for rotations of reference frame axes as expressed in Equations N. As shown in FIG. 4, weighting devices 22, 23 and 24 are coupled to registers 4, 5 and 6, respectively, to read and weight the numbers stored therein. The numbers are weighted depending on the value of incremental signals δ_I having signs represented by σ_I . These incremental signals δ_I are preferably pulses each representative of equal increments of rotation of the reference frame about one of its axes I, II or III. The sign signals denoted generally as σ_I are preferably voltages whose levels are indicative of the forms of the associated increments δ_I . The weighted values of numbers from devices 22, 23 and 24 are each applied to a different add and a different subtract device. These add and subtract devices are denoted 25 to 30 and are controlled by δ_I pulses and σ_I signals so that weighted increments of each stored number are added or subtracted to others of the stored numbers. More specifically, weighting device 22, which detects $\Delta R'_{Ix}$, feeds add device 28 and subtract device 29 which alters stored numbers R_{Iix} and R_{IIIx} , respectively. At the same time, device 23 detects $\Delta R'_{Iy}$ and feeds add device 30 and subtract device 25, which alters stored numbers R_{IIix} and R_{Ix} and device 24 detects $\Delta R'_{Iz}$ and feeds add device 26 and subtract device 27 which alter stored numbers R_{Ix} and R_{IIIz} .

The weighting of numbers from registers such as 4, 5 and 6 by devices 22, 23 and 24 depends upon the incremental angle of rotation represented by each δ_I pulse, just as the weighting by devices 19, 20 and 21 depends, upon the incremental angle of rotation represented by each δ_j pulse. For example, if each δ_I pulse represents an angle increment of rotation of the reference frame about one of its axes of 2^{-6} radians, devices 22, 23 and 24 would weight numbers R_{Ix} , R_{Iix} and R_{IIIx} by effectively multiplying them by 2^{-6} .

The general method shown in FIG. 4 includes only three of the registers shown in FIG. 3 with various means coupled thereto for altering numbers in those registers to accompany for reference frame rotations. Consequently, three of Equations N are computed by the system shown in FIG. 4 and these are the equations for $\Delta R'_{Ix}$, $\Delta R'_{Iy}$ and $\Delta R'_{Iz}$. The remaining of the Equations N can obviously be computed by a similar method represented by similar devices coupled to registers 7 to 12 of FIG. 3.

A general method for computing velocity and position of body 1 in the direction of reference frame axes which are rotated so as to be at all times in the directions of earth longitude, latitude and gravity, is shown in FIGS. 6a, 6b and 6c. An understanding of the operation of the general system shown in these figures is aided by the spacial diagram in FIG. 5.

Referring to FIG. 5 there is shown the earth's globe 31 spinning about its axis 32 at a rate Ω . Body 1 is located at a position which may be, for example, represented by latitude line 33 and longitude line 34, both at a distance A from the center of the earth. The reference frame axes I, II and III are shown in the directions of longitude, latitude and gravity while body axes x , y and z are not shown, but may have any orientation relative to the reference frame axes. The angles of latitude and

longitude represented by lines 33 and 34 are denoted λ and L and the distance of body 1 from the center of the earth is denoted A . When body 1 moves at velocities V_I , V_{II} and V_{III} , in the directions of axes I, II and III, respectively, it is evident that λ , L and A change as the following functions of these velocities;

(O)

$$\begin{aligned}\Delta\lambda &= V_I \frac{(\Delta t)}{A} \\ \Delta L &= V_{II} \frac{(\Delta t)}{A \cos \lambda} \\ \Delta A &= V_{III} (\Delta t)\end{aligned}$$

In order to maintain axes I, II and III at all times in the directions of earth longitude, latitude and gravity, the reference frame must be rotated to account for the motions of body 1 in space and the rotational motion of the earth. As a reasonable approximation, the increments of reference frame rotation about each of its axes, denoted generally as δ_i , can be represented in terms of ΔL , $\Delta\lambda$ and Ω in the following manner:

(P)

$$\begin{aligned}\delta_I &= \Delta L \cos \lambda + \Omega \Delta t \cos \lambda \\ \delta_{II} &= \Delta\lambda \\ \delta_{III} &= \Delta L \sin \lambda + \Omega \Delta t \sin \lambda\end{aligned}$$

Upon examination of Equations O and P above it is evident that the increments δ_i can be obtained if λ , L and Ω are known.

Referring next to FIGS. 6a, 6b and 6c there is shown in block diagram form the general method of computing body velocity and position to store numbers representing V_I , V_{II} , V_{III} , L , λ and A . The general method shown in these figures produces δ_i and σ_i signals representing increments of reference frame rotation in accordance with Equations O and P.

As shown in FIG. 6a, there are nine add devices 35 to 43 each serving to add a different one of the nine incremental numbers ΔR_{ij} , in response to different incremental velocity pulses, denoted as v_x , v_y and v_z , to registers 44, 45 and 46, which stored V_I , V_{II} and V_{III} , respectively. These v_x , v_y and v_z pulses each represent equal increments of velocity of body 1 parallel to its axes x , y and z , respectively, and each is accompanied by an associated ρ_j signal indicating the sense or direction of the v_j pulse. Thus, sign signals ρ_x , ρ_y and ρ_z indicate the sense or direction of incremental velocity pulses v_x , v_y and v_z , respectively. The v_j pulses and their associated ρ_j signals are derived from accelerometer devices such as shown in FIG. 9, each of which includes an inertia sensor which is sensitive to accelerations of body 1 in the direction of a different one of its axes x , y or z . As shown in FIG. 6a, add devices 35, 36 and 37 are controlled by v_x pulses, devices 38, 39 and 40 are controlled by v_y pulses and devices 41, 42 and 43 are controlled by v_z pulses. Devices 35, 38 and 41 feed incremental numbers ΔR_{Ix} , ΔR_{Iy} and ΔR_{Iz} to V_I register 44 while devices 36, 39 and 42 feed V_{II} register 45 and devices 37, 40 and 43 feed V_{III} register 46. The add devices are also controlled by ρ_j signals which reverse the signs of ΔR_{ij} numbers when associated v_j pulses represent negative increments of body velocity.

A number representative of gravitational acceleration and denoted G is added to V_{III} register 46 by add device 47 at regular intervals. This accounts for gravitational forces acting on body 1. The velocities stored in registers 44, 45 and 46 are read and weighted by weighting devices 48, 49 and 50 and added to $V_{I/A}$ register 51, $V_{II/A} \cos \lambda$ register 52 and A register 53 via add devices 54, 55 and 56, respectively. Add devices 54 and 55 are controlled by special detecting circuits for detecting $\Delta\phi$ and $\Delta\theta$ in the reciprocal computer shown in FIG. 6b. This reciprocal computer serves to compute numbers representative of the quantities $(1/A)$ and $(1/A \cos \lambda)$ which are denoted for simplicity as quantities ϕ and θ , respectively.

Referring to FIG. 6b, the quantities ϕ and θ are stored in registers 57 and 58 which respond to add devices 59 and 60, respectively. Detecting circuits 61 and 62 are coupled to add circuits 59 and 60 to detect predetermined increments applied to registers 57 and 58. Detecting devices 61 and 62 detect said predetermined increments and generate pulses, each pulse representative of an increment. These detectors also generate sign signals representative of the sign of the increments represented by pulses. Consequently, the output from detector 61 consists of pulses each representative of equal increments of the quantity ϕ and a signal representative of the sign of the increments. The pulses from detector 68 are herein referred to as $\delta_{\Delta\phi}$ and the sign signals from detector 68 are herein denoted as $\sigma_{\Delta\phi}$. Detector 62 detects predetermined increments added to the quantity θ in register 58 producing pulses denoted $\delta_{\Delta\theta}$ and accompanying sign signals denoted $\sigma_{\Delta\theta}$. On the other hand, add device 56 is controlled by time increment pulse denoted Δt .

Turning again to FIG. 6a, the quantities stored in V_I/A register 51, $V_{II}/A \cos \lambda$ register 52 and A register 53 are continually added to as ϕ and θ change. These numbers are then weighted by weighting devices 63 and 64 and fed to L register 65 and λ register 66 via add devices 67 and 68, respectively at regular intervals of time denoted Δt . This is accomplished by controlling add devices 67 and 68 with Δt signals in the same manner that add device 56 is controlled. Consequently, the numbers stored in L register 66, λ register 65 and A register 53 are at all times representative of the longitude, latitude and altitude of body 1 as expressed by Equation O.

Referring again to FIG. 6b there is shown resolver device 69 for obtaining $\sin \lambda$ and $\cos \lambda$. This device includes sine register 70 and cosine register 71 with add devices 72 and 73 coupled to the inputs thereof and weighting devices 74 and 75 for reading and weighting numbers representative of the $\sin \lambda$ and $\cos \lambda$, respectively. The outputs of weighting devices 74 and 75 are applied to registers 71 and 70 via add devices 73 and 72, respectively, and these add devices are controlled by incremental signals from detector 77 of FIG. 6a. Detector 77 responds to add device 67 and produces $\delta_{\Delta\lambda}$ pulses and $\sigma_{\Delta\lambda}$ signals representing predetermined increments of λ . Consequently, resolver 69 operates in response to the output from detector 77 to maintain numbers in registers 70 and 71 representative of $\sin \lambda$ and $\cos \lambda$, the number representative of λ being stored in register 65. The principle of operation of resolver 69 is based on Equations R and S below:

$$\begin{aligned}(R) \quad \Delta \sin \lambda &= (\cos \lambda) \Delta \lambda \\ (S) \quad \Delta \cos \lambda &= -(\sin \lambda) \Delta \lambda\end{aligned}$$

Equations R and S express the differential of $\sin \lambda$ and the differential of $\cos \lambda$, respectively, in incremental rather than differential form. In the operation of resolver 69, $\delta_{\Delta\lambda}$ pulses controlling adders 72 and 73 cause weighted values of $\cos \lambda$ and weighted values of $\sin \lambda$ to be added to $\sin \lambda$ register 70 and $\cos \lambda$ register 71; thereby computing Equations R and S.

Detectors 76 and 78 coupled to add circuits 68 and 56, which in turn feed L register 66 and A register 53, operate in essentially the same manner as detectors 61, 62 and 77. Each of these detectors, 76 and 78 detect predetermined increments which are added to their associated registers. Consequently, the output from detector 76 consists of $\delta_{\Delta L}$ pulses and $\sigma_{\Delta L}$ signals representative of the sign of said pulses. The output of detector 78 consists of $\delta_{\Delta A}$ pulses and $\sigma_{\Delta A}$ signals representative of the sign of said pulses.

Consider next the operation of the ϕ and θ computers shown in FIG. 6b. The ϕ computer consists of A register 53 with weighting means 79 coupled thereto. The output from weighting means 79 is added to $A \cdot \phi$ register 59 by add device 82 each time a $\delta_{\Delta\phi}$ pulse is produced by

detector 61. Consequently, register 81 stores the product A times ϕ which is unity when the system is in equilibrium. The number in register 81 is compared with unity from unity register 83, by subtract device 84. The output of subtract device 84 is fed to ϕ register 57 via add device 59 and, as already stated, given predetermined increments of ϕ are detected by device 61 which controls add device 82.

The θ computer operates in a manner similar to the ϕ computer and consists of $A \cos \lambda$ register 85 which is fed weighted values of $\cos \lambda$ via add device 86. Add device 86 is controlled by δ_{AA} pulses and σ_{AA} signals from increment detector 78 of FIG. 6a. Consequently, the number in register 85 represents $A \cos \lambda$. This number is weighted by device 87 and added to $A \cos \lambda \cdot \theta$ register 88 by add device 89 which is controlled by δ_{AO} pulses and σ_{AO} signals from increment detector 62. Consequently, the number in register 88 represents $A \cos \lambda$ times θ and is unity when the system is in equilibrium. The number in register 88 is compared with unity from unity register 83 by subtract device 90 and the output therefrom is added at regular intervals to θ register 58 via added device 60.

It should be noted that the ϕ and θ computers operate similar to a servo type analog system for computing the reciprocal of an analog signal and the numbers in registers 57 and 58 approach the proper values of ϕ and θ subsequent to increases or decreases in A and $A \cos \lambda$, respectively. If the speed of the system is high this approach will be rapid and if low, it will be slow.

Turning next to FIG. 6c there is shown a system responsive to outputs from the systems of FIGS. 6a and 6b for producing δ_I and δ_{II} pulses accompanied by σ_I and σ_{III} signals in accordance with the expressions in Equation S. As shown, registers 91 and 92 store numbers representative of reference frame rotations about axes I and II, respectively. The numbers in registers 91 and 92 each represent summations of weighted numbers fed to those registers from $\cos \lambda$ register 71 and $\sin \lambda$ register 70 via weighting devices 75 and 74 all shown in FIG. 6b.

As shown in FIG. 6c the output from weighting device 75 is applied to add devices 93 and 94 which feed register 91, add device 93 being controlled by signals from increment detector 76 and add device 94 being controlled by timing signals representing $\Omega \Delta t$. In the same manner, the output from weighting device 74 is applied to add devices 95 and 96 which feed register 92. Add device 95 is controlled by the output of increment detector 76 of FIG. 6a and add device 96 is controlled by $\Omega \Delta t$ signals. Increment detectors 97 and 98 responsive to add devices 93 and 94 and 95 and 96 respectively, serve to detect increments to their associated registers and generate pulses representative of δ_I and δ_{II} . It should be noted that δ_{AA} is the equivalent of δ_I . Consequently, δ_I and σ_I are obtained from increment detector 78 shown in FIG. 6a.

The output from the systems shown in FIGS. 6a, 6b and 6c are the pulses δ_I , δ_{II} and δ_{III} and their associated sign signals σ_I , σ_{II} and σ_{III} . These outputs are applied to a matrix computer shown in FIG. 4 to alter matrix numbers, thereby accounting for reference frame rotations as required to maintain the reference frame axes aligned with longitude, latitude and gravity.

Consider next the operation of a typical one of the gyroscope devices for producing δ_j pulses and σ_j signals in response to rotations of body 1 about one of its axes. Referring to FIG. 7, there are shown the details of a typical gyroscope device comprising a single degree of freedom gyroscope 99 preferably fixed to body 1, so as to be responsive to rotations of body 1 about an axis x , y or z . For example, assume that gyroscope 99 is responsive to rotations about the x axis. When body 1 rotates about its x axis, gyroscope housing 100 will precess on bearings 101 and 102 supporting axle 103 which is orientated in the y axis direction and preferably concentric with the y axis. The precession angle of the gyroscope is detected

as a phase shift of a 5 kc. signal induced in rotor coil 104, fixed to one end of axle 103 by stator coil 105. This phase shifted 5 kc. signal is fed from rotor coil 104 via brush 105a to amplifier 106 and in turn to phase comparing network 107 where it is phase compared with the signal from a 5 kc. oscillator 108 which also energizes coil 105. It can be seen with reference to waveform diagrams of FIG. 18 that δ_j pulses each representing an increment of rotation of 2^{-6} radians can be handled by the matrix computer, described herein with reference to FIGS. 10a, 10b and 10c, at a maximum rate of about 5000 per second or approximately 192 μ secs. between δ_j pulses. This will accommodate body 1 rotation rates of about 2^6 radian/sec. which is adequate for most applications. Therefore oscillator 108 is preferably 5 kc.

The output of network 107 is a pulsating D.C. signal whose D.C. sign and magnitude are indicative of the phase difference between input signals. This output is filtered by 5 kc. filter trap 109 and fed to chopper 110 which is controlled by sampling pulse generator 111 generating 5 kc. chopper pulses in response to the output of 5 kc. oscillator 108. The chopped D.C. output signal from chopper 110 is then fed to each of similar reference voltage multivibrators 112 and 113 which are also fed D.C. signals from battery 114, multivibrator 112 being fed a positive voltage from battery 114 and multivibrator 113 being fed a negative voltage from battery 114. The design and operation of multivibrators 112 and 113 may be as described on page 343, volume 19 of Radiation Laboratory Series published by McGraw-Hill. These multivibrators each produce a signal pulse output upon receiving a pulse from chopper 110 which is, in the case of multivibrator 112, more positive than the positive battery voltage fed to multivibrator 112 or, in the case of multivibrator 113, more negative than the negative battery voltage fed to multivibrator 113. The output of multivibrator 112 energizes bistable flip-flop circuit 115 and the output of multivibrator 113 energized bistable flip-flop circuit 116. Each of these flip-flop circuits, 115 and 116, are reset simultaneously by a signal from 5 kc. standard pulse generator 117 via delay circuit 118. The outputs of one stage of flip-flop circuits 115 and 116 control "and" gates 119 and 120 which gate pulses from standard pulse generator 117 and feed said gated pulses to one end or the other of torquing coil 121 which is inductively coupled to magnet 122 fixed to axle 103, thereby torquing said axle. Thus, the output of chopper 110 consisting of positive or negative pulses causes multivibrators 112 and 113 to energize flip-flop circuits 115 and 116, respectively, when the pulses from chopper 110 exceed predetermined voltage values determined by battery 114 and when flip-flop circuits 115 or 116 are energized, gate 119 or 120 open allowing a signal pulse from standard pulse generator 117 to be applied to one side or the other of torquing coil 121 causing axle 103 to be torqued in such a direction as to oppose the tendency of gyroscope housing 100 to precess in response to a rotation of body 1 about its x axis.

The outputs of "and" gates 119 and 120 are also fed to "or" gate 122a whose output signal consists of δ_x pulses. The sign of the δ_x pulse is represented by the signal output σ_x from one stage of double input bistable flip-flop circuit 123 which is also coupled to the outputs of "and" gates 119 and 120. In one embodiment of this invention which is herein described, the δ_x output from "or" gate 122a and σ_x signal from flip-flop 123 are buffered by a buffer device consisting of special logic circuits. The construction and operation of a typical one of these logic circuits will be described with reference to FIG. 9. Subsequently, the operation of gyro buffer circuit 124 shown in FIG. 7 will be described.

Referring next to FIG. 8 there is shown a typical one of three accelerometer devices for producing pulses representing predetermined increments of velocity of body 1 in the direction of one of its axes x , y or z , for example,

the x axis. This device consists of an accelerometer 125 responsive to accelerations of body 1 in the direction of its x axis. Accelerometer 125 might for example be of the single degree of freedom spring retained type, shown in FIG. 8, or any other suitable design known to the art producing a D.C. signal indicative of acceleration.

In operation, the D.C. output signal from accelerometer 125 is fed to reactance circuit 126 of 800 kc. oscillator 127a to control the frequency of said oscillator about ± 20 kc. so that the frequency is indicative of acceleration. The signal output of oscillator 127a is shaped by squaring circuit 128a which may be, for example, a cathode coupled double ended clipper circuit. The output of circuit 128a is fed to differentiating circuit 129a which produces positive and negative spikes.

A stable 800 kc. oscillator 127b which preferably has a piezoelectric quartz crystal as its resonant circuit feeds another squaring circuit 128b which in turn feeds another differentiating circuit 129b producing positive and negative peaks. The positive peaks from circuit 129b are at a repetition rate of 800 kc. plus or minus the frequency change produced by the effects of an acceleration of body 1 parallel to its x axis. The outputs from circuits 129a and 129b are applied to different sides of double input bistable flip-flop circuit 130 so that positive peak signals from circuit 129a cause stage 130a to conduct while positive peak signals from circuit 129b cause stage 130b to conduct. Circuits 129a and 129b also feed spike signals to "and" gates 131a and 131b, respectively, and these gates are controlled by stages 130a and 130b, respectively, so that when the frequency of oscillator 127a is higher than 800 kc., positive pulses will be passed by gate 131a at regular intervals and said interval will vary directly with the frequency difference between the outputs from oscillator 127a and crystal oscillator 127b. Similarly, when the frequency of oscillator 127a is lower than 800 kc., positive pulses will be passed by gate 131b at regular intervals depending on the frequency difference in signals from said oscillators. The response of reactance circuit 126 and, thus, oscillator 127a, to a D.C. voltage from accelerometer 125 is such that an acceleration of body 1 in the direction of the axis x causes an increase in the frequency of oscillator 127a over and above 800 kc. which is its frequency when the input to the reactance circuit is ground and the increase in frequency is directly proportional to the acceleration.

The output of gates 131a and 131b are coupled via diodes 132a and 132b, respectively, yielding v_x pulses each representative of equal increments of velocity of body 1 in its x direction. As can be seen from the interval T_{ij} waveforms of FIG. 18 in the embodiment herein described, these v_x pulses cannot occur more frequently than once every 192 μ secs. (the repetition rate of T_{ij} intervals). Consequently, if each pulse represents an increment of velocity of 2^{-3} ft./sec. then the system is capable of responding to an acceleration of 21 times gravity. Each of these outputs are also fed to different stages of double input bistable flip-flop circuit 133 so that sign signal ρ_x indicates that the last v_x pulse represents a positive increment of velocity (in the direction of axis x) when stage 133a of flip-flop circuit 133 conducts. The v_x pulses and ρ_x signals are employed as already described with reference to FIG. 6a. However, in an embodiment of this invention, the v_x pulses from diodes 132a and 132b and the ρ_x signal from flip-flop 133 are buffered by a buffer device consisting of special dynamic logic circuits. A typical dynamic logic circuit will be described next with reference to FIG. 9 and, subsequently, the operation of buffer device 134 shown in FIG. 8, as well as device 124 of FIG. 7, will be described. It is to be understood that similar accelerometers and circuits are used for sensing accelerations along the y and z axes.

The various functions indicated in FIGS. 3, 4, 6a, 6b and 6c may be performed in many ways using, for example, static or dynamic logic circuitry. The systems

shown in these figures have many redundancies of equipment, such as a multiplicity of adders, subtracters, gates and registers, etc., many of which can be eliminated in more sophisticated arrangements. One form of such an arrangement to compute the numbers R_{ij} is described herein with reference FIGS. 10a, 10b and 10c wherein is shown a matrix computer comprising dynamic logic circuits controlled by various timing pulses from an electronic clock to perform the functions hereinabove described with reference to FIGS. 3 and 4. The arrangement includes three magnetostrictive storage devices to store the numbers R_{ij} in serial binary form. The matrix computer shown is responsive to buffered signals from gyroscope devices having gyros fixed to the x , y and z axes of body 1. The buffered pulses from the gyroscope devices initiate additions to and subtractions from the nine numbers R_{ij} as prescribed by the nine Equations M and nine Equations K. Details of one embodiment for computing velocities V_I , V_{II} , and V_{III} and positions λ , L and A is shown in FIGS. 11 through 17 comprised of a multitude of dynamic circuits responsive to the outputs from accelerometer devices such as already described with reference to FIG. 8 and to the incremental numbers ΔR_{ij} from the matrix computer.

The operation of a typical one of the numerous dynamic logic circuits comprising the matrix and velocity and position computers and buffer circuits in the gyroscope and accelerometer devices can be understood with reference to the details of such a logic circuit shown in FIGS. 9a, 9b and 9c, the principles of which are well known and described in some detail in an article by R. W. Brooks on page 147 of the March 1957 issue of "Instruments and Automation." There is also some discussion of dynamic logic circuits on page 415 in "Pulse and Digital Circuits" by Millman and Taub, published by McGraw-Hill.

Referring next to FIG. 9a there is shown a typical dynamic logic circuit 135 having an assertive output and a negative output η . The external inputs to circuit 135, for example, A' , B' and C' may be intermittent, continuous or otherwise pulsed signals, and the logic performed by this circuit is expressed by the logic equations for α and η shown at FIG. 9a. The same dynamic logic circuit 135 is shown in detail in FIG. 9b comprising input "and" circuits 136 and 137, each of which produces an output in response to simultaneously receiving pulses or signals from the different inputs coupled thereto. The "and" circuit 136 is fed α and C' signals, while "and" circuit 137 is fed A' and B' signals. The outputs of circuits 136 and 137 are coupled together and fed to a similar "and" circuit 138 which is continuously fed one megacycle clock pulse, T_n , from the electronic clock described herein with reference to FIGS. 20a and 20b so that said clock pulses appear at the output of circuit 138 when they are in coincidence with an output from circuit 136 or 137. The output of "and" circuit 138 is fed to amplifier 139 whose output is fed to transformer 140 which has two secondary windings, 141 and 142, coupled together by battery 143 having one terminal grounded. The output from windings 141 and 142 are fed to delay circuits 144 and 145, respectively, which delay pulses from their respective coils to yield α and η pulses synchronized with the next clock pulse. A waveform diagram of α and η is shown in FIG. 9c from which it may be seen that while α is at ground potential between pulses, η is at battery 135 voltage and subsequently when α swings toward battery 143 voltage in response to a pulse output from amplifier 139, η swings toward ground. In other words, battery voltage output at terminal α indicates that the logic equation for α , shown in FIG. 9a, is satisfied whereas battery voltage output at terminal η indicates that the logic equation for η is not satisfied. On the other hand, the converse of these conditions exists where α and η are at ground.

Turning again to FIGS. 7 and 8, buffer circuits 124 and 134 consisting of dynamic logic circuits operate as fol-

lows: In FIG. 7, the output of "or" gate 122 and flip-flop circuit 123 are applied to dynamic circuits 146, 147 and 148 as shown. These circuits are also responsive to various timing pulses from an electronic clock described herein with reference to FIGS. 20a and 20b and shown in waveform diagrams of FIG. 18. Circuit 146 is responsive to δ_x pulses from "or" gate 122, $\bar{T}'_1$ pulses from the clock and its own assertive output α_{146} . Consequently, the logic performed by circuit 146 is as follows:

$$(T) \quad \alpha_{146} = (\delta_x) v(\bar{T}'_1 \cdot \alpha_{146})$$

In other words, circuit 146 produces an assertive output α_{146} each time a δ_x pulse occurs and thereafter until a T'_1 pulse occurs.

Circuit 147 is responsive to δ_x pulses, α_{146} , T'_{96} and $\bar{T}'_{48}$, performing the following logic function:

$$(U) \quad \alpha_{147} = (\alpha_{146} \cdot \bar{T}'_{48}) v(\delta_x \cdot T'_{96}) v(\alpha_{146} \cdot T'_{96})$$

The α output from circuit 146 is also fed to circuit 148 along with $\bar{T}'_{48}$, T'_1 , σ_x (from flip-flop circuit 123) and the α output from circuit 148. The logic performed by circuit 148 is described by the following logic equation:

$$(V) \quad \alpha_{148} = (\alpha_{146} \cdot \bar{T}'_{48}) v(\sigma_x \cdot \alpha_{146} \cdot T'_1)$$

In other words, the action of circuits 146 and 147 is to first produce clock pulses following the occurrence of a δ_x pulse from "or" gate 122; these clock pulses to continue until a T'_1 pulse is produced by the clock. The clock pulses thus produced are denoted α_{146} and are applied to circuit 147 producing a pulse output from circuit 147 upon the occurrence of a T'_{96} clock pulse. Thereafter, circuit 147 will continue to produce clock pulses until a T'_{48} pulse occurs. Thus, referring to waveforms of FIG. 18, circuit 148 produces an α output subsequent to the occurrence of a δ_x pulse from "or" gate 122; this α output occurring during the next interval of T'_1 to T'_{48} . The pulses thus produced in the output of circuit 147 are buffered δ_x pulses and will be hereinafter referred to simply as δ_x clock pulses to distinguish them from the δ_x pulses such as produced by "or" gate 122.

The operation of circuits 146 and 148 is somewhat similar. Circuit 148 produces an α output upon simultaneously receiving a signal from flip-flop circuit 123, an α output from circuit 146 and a T'_1 pulse. Subsequently, circuit 148 produces clock pulses until the next T'_{48} pulse occurs. Thus, it is seen circuit 148 produces pulses during the same interval that circuit 147 produces pulses. The output of circuit 148 is a buffered σ_x signal herein referred to as σ_x clock pulses. It should be noted that the α output from circuit 148 consists of ground pulses when δ_x represents a positive increment of rotation and it consists of battery pulses when δ_x represents a negative increment of rotation (refer to FIG. 9c for the significance of ground and battery pulses).

Turning next to buffer circuit 134 in FIG. 8, there is shown logic circuits 149, 150 and 151 producing ν_x , ρ_x , and $\bar{\rho}_x$ clock pulses in response to the ν_x pulses from diodes 132a and 132b and the ρ_x signals from flip-flop circuit 133. Circuits 149 and 151 operate very much in the same manner as circuits 146 and 148 described above with reference to FIG. 7. Circuit 149 responds to ν_x pulses, $\bar{R}$ pulses and its own assertive output, producing an α output subsequent to the occurrence of a ν_x pulse, consisting of clock pulses until the subsequent R pulse occurs. The R pulses are obtained from the clock shown in FIGS. 20a and 20b and are actually every other T'_{96} pulse. The α output from circuit 149, denoted α_{149} , is applied to circuit 150 as well as R pulses, $\bar{R}$ pulses and the α output from circuit 150. Consequently, the α output from circuit 150 consists of clock pulses during the interval between successive R pulses which follows the occurrence of a ν_x pulse. This α_{150} output is herein referred to as ν_x clock pulses. Logic circuit 151 responds to α_{150} , ρ_x signals from flip-flop circuit 133, R pulses, $\bar{R}$

pulses and the assertive output, α_{151} , from circuit 151. Consequently, α_{151} consists of clock pulses during the same interval that clock pulses are produced in the output of logic circuit 150. More specifically, the α output from circuit 151 consists of ground pulses when ν_x pulses from diodes 132a and 132b represent a positive increment of velocity of the body in the direction of its x axis, and this output consists of battery pulses when ν_x represents negative increments of velocity of the body in the direction of its x axis.

Turning next to FIGS. 10a, 10b and 10c there is shown a matrix computer operating generally as already described with reference to FIGS. 3 and 4. This computer employs dynamic logic circuits for performing the functions set forth in FIGS. 3 and 4 and serial binary storage devices for storing the numbers R_{ij} . The matrix computer is responsive to δ_x , δ_y , δ_z and δ_I , δ_{II} , δ_{III} clock pulses accompanied by their associated σ clock pulses representing positive or negative increments of rotation. A typical source of δ_I clock pulses, for example, δ_x , and associated σ_x clock pulses has already been described with reference to FIG. 7. Sources of δ_I clock pulses will be described with reference to FIGS. 16 and 17. The buffer circuit in FIG. 17 for obtaining δ_I clock pulses is exactly the same as buffer circuit 124 of FIG. 7.

The matrix computer in FIGS. 10a, 10b and 10c serves to compute and store the nine coefficients R_{ij} described by the nine Equations M and nine Equations K. All clock pulse inputs are depicted in waveform diagrams of FIGS. 30 18 either as pulses or intervals of pulses. The matrix computer consists of dynamic storage devices 152, 153, and 154 which are identical in construction and operation, each serving to store three different ones of the nine cosine numbers R_{ij} . Since these storage devices are identical in construction and operation, the details of device 152 only will be described herein. Device 152 is, for example, comprised of a magnetostrictive delay line 155 which serves to delay each pulse input from coil 156 inductively coupled to one end thereof, 48 microseconds before it is detected at coil 157 which is inductively coupled to the other end and feeds amplifier 158. Since the dynamic system herein described runs at one megacycle, as established by the one μ sec. clock pulses, magnetostrictive delay line 155 is capable of storing 48 bits of information at any particular instant, which in this embodiment describe three different numbers each of 16 binary bits including one bit representing the sign of the number. Three such numbers, each comprised of 16 binary bits are shown in time relationship and denoted inputs to amplifier 158 in the waveform diagrams of FIG. 19 wherein it is seen that the first or least significant binary bit of number R_{ix} coincides in time with clock pulse T_1 . Pickup coils 159, 160 and 161 are also inductively coupled to magnetostrictive delay line 155 at such points to detect a given pulse introduced by coil 156 eight, twenty-four and forty microseconds, respectively, after that same pulse is introduced by coil 156 and feed the detected pulse to amplifiers 162, 163 and 164 respectively. The outputs of amplifiers 162, 163 and 164 are fed to dynamic fill-in circuits 165, 166 and 167 which serves to blank out the first 8 least significant binary bits of each of the three numbers stored in magnetostrictive delay line 155 and fill in 8 clock pulses following the sixteenth or sign bit of a number, provided that sign bit indicates that the number is negative. This is accomplished by employing what are herein referred to as fill-in pulses T_w and $\bar{T}_w$ shown in FIG. 19 which are generated by the electronic clock. The logic of a fill-in circuit, for example, circuit 166, may be expressed by the following logic equation:

$$70 (W) \quad \alpha_{166} = \Delta R_{ix} = (R_{ix} \cdot T_w) v(\alpha_{166} \cdot \bar{T}_w)$$

As seen in Equation W above, the α output from circuit 166 is equivalent to a filled-in number ΔR_{ix} which is an increment of binary number R_{ix} stored in magnetostrictive device 152 and is shown in waveform diagram in FIG.

19 where it is denoted filled-in ΔR_{Ix} . As expressed by logic Equation W above, the filled-in ΔR_{Ix} output consists of a pulse upon the simultaneous arrival at the input to circuit 166 of T_w pulse and one binary bit pulse from number R_{Ix} or upon the simultaneous arrival of an α_{166} pulse and a $\bar{T}_w$ pulse at the input to circuit 165. Thus, the effect of circuit 166 in conjunction with coil 160 is to shift the number R_{Ix} 8 places, dropping the first 8 least significant binary bits and filling in the 8 binary bit spaces following each shifted number with clock pulses only when the number is negative. Fill-in circuits 165 and 167 operate in the same manner as circuit 166. However, while the output at a particular instant, from circuit 166 is filled-in ΔR_{Ix} the outputs from circuits 165 and 167 will be filled-in ΔR_{Ix} and ΔR_{IIX} , respectively.

Meanwhile, magnetostrictive storage devices 153 and 154 feeding fill-in circuits 168, 169 and 170 and 171, 172 and 173, respectively, function in the same manner as magnetostrictive storage device 152 and circuits 165, 166 and 167. Circuits 168 to 173 perform the same functions in computing the shifted and filled-in numbers ΔR_{Iy} and ΔR_{Iz} as do circuits 165, 166 and 167 which compute the filled-in numbers ΔR_{Ix} .

One of the operations of gating circuits 174 and 175 in FIG. 10a is to condition the outputs from circuits 170 and 173 in response to δ_y and δ_z clock pulses and the σ_y and $\bar{\sigma}_y$ and σ_z and $\bar{\sigma}_z$ clock pulses, respectively, from circuit such as 124 in FIG. 7, so as to compute the numbers ΔR_{Ix} , ΔR_{IIX} and ΔR_{IIX} as expressed in Equations K. For example, assume that at a given instant a 16-bit word R_{Ix} is being fed to circuit 167 in serial form, the least significant bit first, while at the same given instant, numbers R_{Iy} and R_{Iz} are being fed to circuits 170 and 173, respectively. The first eight least significant bits of each of these numbers are removed and pulses substituted after the remaining bits creating the filled-in incremental numbers. Thus, the logic equations, at said instant, which are performed by circuits 167, 170, and 173 are expressed by equations:

$$(X) \quad \begin{aligned} \alpha_{167} = \Delta R_{Ix} &= (R_{Ix} \cdot T_w) v(\alpha_{167} \cdot \bar{T}_w) \\ \alpha_{170} = \Delta R_{Iy} &= (T_{Iy} \cdot T_w) v(\alpha_{170} \cdot \bar{T}_w) \\ \alpha_{173} = \Delta R_{Iz} &= (R_{Iz} \cdot T_w) v(\alpha_{173} \cdot \bar{T}_w) \end{aligned}$$

The purpose of circuits 170 and 173 at the given instant is to feed filled-in binary numbers ΔR_{Iy} and ΔR_{Iz} , respectively, to dynamic serial adder circuits 176 and 177, via delay circuits 178 and 179, respectively, in response to δ_y clock pulses and δ_z clock pulses, respectively. The function of dynamic serial adder circuits 176 and 177 at said given instant is to add or subtract ΔR_{Iz} and ΔR_{Iy} to R_{Ix} upon the occurrence of δ_y and δ_z increments of body rotation, thereby performing the operation described by the first three of Equations K and the first three of Equations M.

As stated hereinabove, coil 161 detects each binary bit eight microseconds before coil 157 detects the same bit. Since the numbers stored in the magnetostrictive device 152 in serial form one after the other are detected by the coils, the least significant binary bit first, the number detected by coil 161, say for example, shifted number ΔR_{Ix} , will actually be 2^{-8} times the number R_{Ix} detected by coil 157. Likewise, and in the same manner, the binary serial numbers fed to circuits 170 and 173 from storage devices 153 and 154 are thereby reduced by a factor 2^{-8} . The purpose of delay circuits 178 and 179 is to delay the gated output signals from circuits 170 and 173, respectively, so that the serial binary numbers fed from them to adders 176 and 177 are shifted only six microseconds with respect to the number R_{Ix} to which they are added or subtracted. Thus, delay circuits 178 and 179 add whatever delay is necessary, along with the inherent delays in the gating circuits 174 and 175 to cause the six microsecond shift so that the significance of each δ_i pulse from a gyro device is maintained as 2^{-6} radians per pulse. Some of

the logic performed by gating circuits 174 and 175 at said given instant, denoted interval T_a , is expressed by the following two logic equations:

$$5 \quad (Y) \quad \begin{aligned} \alpha_{174} &= [(\delta_y \cdot \sigma_y \cdot \Delta R_{Iz}) v(\delta_y \cdot \bar{\sigma}_y \cdot \Delta R_{Iz})] \cdot T_a \\ \alpha_{175} &= [(\delta_z \cdot \sigma_z \cdot \Delta R_{Iy}) v(\delta_z \cdot \bar{\sigma}_z \cdot \Delta R_{Iy})] \cdot T_a \end{aligned}$$

As can be seen from the first of logic Equations Y above, during the interval T_a an assertive output from circuit 174, indicative of filled-in ΔR_{Iz} , occurs when δ_y clock pulses, σ_y clock pulses and filled-in ΔR_{Iz} pulses simultaneously arrive at the input of circuit 174 or when δ_y clock pulses, $\bar{\sigma}_y$ clock pulses and filled-in ΔR_{Iz} pulses simultaneously arrive. This assertive output α_{174} is indicative of ΔR_{Iz} and its negation, η_{174} , is indicative of $\Delta \bar{R}_{Iz}$. Both outputs are fed to serial adder 177 which has the effect of adding the number ΔR_{Iz} to the number R_{Ix} when the δ_y increment represents a positive rotation of body 1. On the other hand, if the σ_y clock pulse input to circuit 174 are not ground pulses, as when δ_y clock pulses represent a positive rotation of body 1, but rather when σ_y is comprised of clock pulses swinging to battery from ground, then the complement of serial binary number ΔR_{Iz} , denoted $\Delta \bar{R}_{Iz}$ will be added to the number R_{Ix} by the action of the adder 171; thereby effectively subtracting ΔR_{Iz} from R_{Ix} . During the interval T_a , gating circuit 175 operates in a manner similar to circuit 174 to gate the filled-in number ΔR_{Iy} in response to δ_z clock pulses and the sign of δ_z as represented by σ_z and $\bar{\sigma}_z$ clock pulses, so that the number ΔR_{Iy} is added or subtracted to the output of adder 177 by the action of adder 176 to thereby complete computation of the first one of Equations K and the first one of Equations M. The interval T_a is shown in the waveforms of FIG. 18.

35 Binary serial adders 174 and 175 associated with magnetostrictive storage device 151, as well as the other adders shown in FIGS. 10b and 10c associated with storage devices 152 and 153 may operate as any of the high speed serial adders known to the art such as, for example, described on page 461 of the March 1957 edition of "Instruments and Automation" published by the Instruments Publishing Company of Pontiac, Illinois.

In FIGS. 11a, 11b, 12a, 12b and 13, there is shown the details of circuitry for computing the functions already described with reference to FIG. 6a. This circuitry consists essentially of dynamic logic circuits and magnetostrictive type storage devices for producing the pulses indicative of ΔL , $\Delta \Delta$ and ΔA which are the outputs from detecting devices 76, 77 and 78, respectively, of FIG. 6a. Turning first to FIGS. 11a and 11b, there is shown the details of the latitude circuits shown functionally in FIG. 6a. The latitude circuits consist of multiple input gate 180 responsive to inputs as shown. The logic performed by gate 180 is apparent from the grouping of the inputs to individual "and" circuits, the outputs of these "and" circuits being fed to an "or" circuit just as already described with reference to FIG. 9. The six "and" gates comprising the input to gate circuit 180 are grouped in pairs; each pair being fed special timing signals from the clock. For example, the first pair of "and" inputs responsive to filled-in numbers ΔR_{Ix} and $\Delta \bar{R}_{Ix}$ are also responsive to interval signal T_{Ix} . The second pair of "and" gate inputs to gating circuit 180 responsive to filled-in numbers ΔR_{Iy} and $\Delta \bar{R}_{Iy}$ are also responsive to interval signal T_{Iy} and the third group, responsive to filled-in numbers ΔR_{Iz} and $\Delta \bar{R}_{Iz}$ are also responsive to signal T_{Iz} . Interval signals T_{Ix} , T_{Iy} and T_{Iz} are shown in wave form diagrams of FIG. 18. From these waveforms it is apparent that the sequence of T_{Ix} , T_{Iy} and T_{Iz} are in coincidence with the outputs from circuits 167, 170 and 173, respectively, when these circuits are producing filled-in numbers ΔR_{Ix} , ΔR_{Iy} and ΔR_{Iz} , respectively. It is also apparent from waveforms in FIG. 18 that v_x clock pulses are in coincidence with T_{Ix} , v_y clock pulses are in coin-

cidence with T_{ix} and v_z clock pulses are in coincidence with T_{iz} . Consequently, the output from gating circuit 180 will consist of the weighted and filled-in number ΔR_{ix} subsequent to the occurrence of a v_x pulse representing a given increment of velocity of the body in the x direction and this filled-in number ΔR_{ix} will appear in the output of circuit 180 during the interval of T_{ix} pulses. Likewise, and in the same manner, the weighted and filled-in number ΔR_{iy} will appear in the output of circuit 180 during the interval of T_{iy} pulses following the occurrence of a v_y pulse representative of an increment of velocity of the body in the direction of its y axis. Also, a filled-in and weighted number ΔR_{iz} will appear in the output of circuit 180 during the interval of T_{iz} subsequent to the occurrence of an v_z pulse representative of an increment of velocity of the body in the direction of its Z axis. The method of generating the pulse groups T_{ix} , T_{iy} and T_{iz} will be described later with reference to the clock in FIGS. 20a and 20b. It should be noted that only one of the filled-in and weighted numbers ΔR_{ii} appearing in the output of gate circuit 180 can occur during the interval that the clock counts from 1 to 48. Furthermore, any particular filled-in and weighted number, for example, ΔR_{ix} can appear in the output of gating circuit 180 only once while the clock counts to 96 twice in a row. This is seen in the waveforms of FIG. 18 showing the closest spacing between T_{ix} groups of pulses as being a frame during which the clock counts from 1 to 96 twice. A fourth group of timing pulses denoted T_g are also shown in the waveforms of FIG. 18 thus making four groups of timing pulses, namely, T_{ix} , T_{iy} , T_{iz} and T_g within each frame.

In view of the above description of the gating circuit 180 it is apparent that a weighted and filled-in number ΔR_{ij} can appear in the output of circuit 180 only during the first sixteen counts of the clock, in each 48 consecutive counts. Magnetostrictive storage device 181 serves to store a 48-bit number representative of the velocity of the body 1 in the direction of reference frame axis I. Device 181 responds to pulse inputs from coil 182 which are detected 48 microseconds later by coil 183 and applied to amplifier 184. The α and η outputs from amplifier 184 are applied to serial binary adder 185 along with the α and η outputs from gating circuit 180. The purpose of adder 184 is to add the filled-in number ΔR_{ij} appearing in the output of gating circuit 180 to the number V_I already stored in magnetostrictive delay line 181 following the occurrence of a v_j pulse from an accelerometer device such as shown in FIG. 8. The lower case m and lower case l on either end of device 181 indicate the location of the most and least significant binary bits when device 181 stores a complete 48-bit number.

The number V_I is weighted by detecting serial bits representing that number by coil 186 located with relation to device 181 so as to detect a binary bit 32 microseconds after the introduction of said binary bit by coil 182 at one end of device 181. Each pulse bit detected by coil 186 is amplified by amplifier 187 and fed to dynamic fill-in circuit 188. Dynamic fill-in circuit 188 operates in much the same manner as other dynamic fill-in circuits already described; however, it is responsive to T_w and $\bar{T}_w$ fill-in pulses as well as its own assertive output and the output from amplifier 187. As can be seen from waveforms in FIG. 19 the action of dynamic fill-in circuit 188 responsive to T_w type of fill-in pulses is to shift the 48 bit binary number V_I stored in device 181, fifteen binary places thereby effectively multiplying a number V_I by 2^{-15} . Another function of fill-in circuit 188 is to fill-in the shifted number subsequent to the occurrence of the most significant bit of such shifted number. As already described, the 48-bit number V_I introduced by coil 182 into delay device 181 is introduced as the least significant bit first followed by the greater and greater significant bits and ending with a pulse representative of the sign of the number V_I . Consequently, the 48th or 75

last bit introduced by coil 182 to delay device 181 represents the sign of the number V_I and as already stated, when this last bit is represented as a pulse then it is indicated that the number V_I is negative. Consequently, 5 when the last bit representing the sign of the shifted number is applied by amplifier 187 to fill-in circuit 188 a train of 12 clock pulses will appear in the output of circuit 188 subsequent to the shifted number V_I , when V_I represents a negative number and no such train of 12 pulses will appear when V_I represents a positive number. 10 The operation and purpose of fill-in circuit 188 is very similar to the operation of other fill-in circuits already described, such as fill-in circuit 166, except that the shifted number fed thereto is larger and shifted a different amount 15 and a different number of fill-in clock pulses are added. The output of fill-in circuit 188 is fed to serial binary adder 189 via gate 190 and delay circuits 191. Gate 190 is controlled by $\delta_{\Delta\phi}$ clock pulses, which are buffered $\delta_{\Delta\phi}$ pulses and accompanying sign clock pulses denoted 20 $\sigma_{\Delta\phi}$ and $\bar{\sigma}_{\Delta\phi}$. The $\delta_{\Delta\phi}$ pulses each represent given predetermined increments of the value ϕ which is stored as a serial binary number in a magnetostrictive type storage device. These given predetermined increments are represented as 25 pulses and are buffered as will be described later with reference to FIG. 15a, producing the mentioned $\delta_{\Delta\phi}$ clock pulses. This buffering is such that the $\delta_{\Delta\phi}$ clock pulses are in coincidence with the shifted and filled in serial number appearing in the output of fill-in circuit 188. The logic performed by gate 190 is represented by 30 the following logic equation:

$$(Z) \quad \alpha_{190} = (\Delta V_I \cdot \delta_{\Delta\phi} \cdot \bar{\sigma}_{\Delta\phi}) \vee (\Delta \bar{V}_I \cdot \delta_{\Delta\phi} \cdot \sigma_{\Delta\phi})$$

The α and η outputs of circuit 190 effectively represent 35 a positive or a negative increment of the stored number V_I which is added to the number $V_{I/A}$, stored in the magnetostrictive storage device 192, following the occurrence of each $\delta_{\Delta\phi}$ pulse representing a given predetermined increment of the value ϕ . This action is described 40 similarly in the latitude part of FIG. 6a with reference to devices 51 and 54 of FIG. 6a.

The output of serial binary adder 189 is applied to the 45 input of device 192 via coil 193 and the output of device 192 is detected by coil 194 and applied to serial binary adder 189 via amplifier 195, amplifier 195 producing an α and an η output in the manner described with reference to FIG. 9b.

Delay circuits 191 serve to further shift the shifted 50 filled in and gated numbers ΔV_I and $\Delta \bar{V}_I$ before adding said numbers to $V_{I/A}$. This further shift is required 55 because it is desired that the quantity ΔV_I which is added to the quantity $V_{I/A}$ represent an increment equivalent to $2^{-12} V_I$. As already described, the location of detection coil 186 with regard to magnetostrictive device 59 storing serial binary number V_I , is such that the shifted number fed therefrom to fill-in circuit 188 represents a value of V_I shifted 15 binary places. Obviously, it is necessary that this shifted filled in and gated number be advanced three binary places to yield the required total 60 shift of 12 binary places. Such an advance is achieved by delaying the serial binary number. Consequently, delay circuits 191 add whatever delay is required in addition to the inherent delays of circuits 188 and 189 to insure that the shifted filled in and gated number coincidentally applied to serial binary adder 189 with the number $V_{I/A}$ from storage device 192, truly represents $2^{-12} V_I$.

In the embodiment of this invention described herein with reference to FIG. 11a, as has already been stated with reference to FIG. 8, each v_j pulse represents an increment of velocity of the body 1 in the direction of one of its body axes of 2^{-3} feet per second. Furthermore, the maximum absolute value of a stored number R_{ij} such as stored in devices 152, 153 or 154 of FIGS. 10a, 10b and 10c, is unity and in these storage devices unity is represented by 15 serial binary bits. Now the process of

multiplication of $v_j \cdot R_{ij}$ is accomplished by the action of gate 180 which responds to shifted and filled in numbers ΔR_{ij} and buffered v_j pulses, each value ΔR_{ij} being added to the number V_I subsequent to the occurrence of a v_j pulse in the accelerometer device of FIG. 8. Since the maximum value of each number R_{ij} represents unity and since each v_j pulse represents an increment of velocity of 2^{-3} feet per second, the maximum incremental number added to the 47-bit serial binary number V_I stored in magnetostrictive device 181 must represent a real value of 2^{-3} feet per second. Furthermore, the maximum binary value of this increment as we have seen from the description of the operation of fill-in circuits 165 through 173 operating in conjunction with spaced pick-up coils for detecting shifted values of numbers stored in devices 152, 153 and 154 is 2^8 . Now since a binary value of 2^8 represents a real value of 2^{-3} feet per second, then a binary value of 2^{27} must represent a real value of 2^{26} feet per second. Therefore, 2^{26} feet per second is the maximum real value of the 48-bit binary number stored in V_I storage device 181.

It will be shown with reference to FIG. 15a that each $\delta_{\Delta\phi}$ pulse represents an incremental value of ϕ of 2^{-40} 1/feet. Since the maximum value of the increment added to the number $V_{I/A}$ each time a $\delta_{\Delta\phi}$ pulse occurs represents 2^{-40} times the maximum real value of V_I , or 2^{-4} radians/sec. by 35 serial binary bits, it is apparent that the maximum 47-bit number representing $V_{I/A}$ represents a maximum real value of 2^8 radians per second.

Turning also to FIG. 11b there is shown more of a method for employing dynamic logic circuits to function as the remainder of the latitude section of FIG. 6a, which in FIG. 6a includes λ register 65 with means coupled thereto for detecting given predetermined increments in the number λ . A shifted value of the number $V_{I/A}$ stored in magnetostrictive device 192 is detected by coil 196 which detects each pulse introduced to said device, 15 binary bits before said pulse is detected in the output of the device and applied to serial binary adder 189. Consequently, the action of pick-up coil 196 is exactly the same with regard to device 192 as the action of coil 186 with regard to device 181. The serial binary number thus detected by coil 196 is herein denoted as $\Delta V_{I/A}$ and is applied to fill-in circuit 197 of FIG. 11b via amplifier 198. Fill-in circuit 197 serves the same function with regard to the increments of the number $V_{I/A}$ as does fill-in circuit 188 with regard to increments of the number V_I . However, in addition fill-in circuit 197 also serves to gate the filled in number $\Delta V_{I/A}$ in accordance with Δt clock pulses from the electronic clock. The interval of these Δt clock pulses are shown in waveform diagrams of FIG. 18. The shifted filled in and gated number $\Delta V_{I/A}$ and $\bar{\Delta}V_{I/A}$, represented as the α and η outputs of circuit 197, are applied to the input of serial binary adder 199 via delay circuits 200. The purpose of adder 199 is to add the shifted filled in and gated number $\Delta V_{I/A}$ to the number λ stored in magnetostrictive storage device 201 and since Δt clock pulses occur at regular intervals, $\Delta V_{I/A}$ is effectively integrated and the integral is represented by the number λ stored in device 201. Since the maximum 47-bit number stored in device 192 has a real value of 2^8 radians/sec. and its weighted value, represented by 35 bits, is added to the 47-bit number λ in device 201 2^{12} times a second, each 35-bit weighted value represents 2^{-12} , 2^8 or 2^{-4} radians. Consequently, the maximum real value of the 47-bit number λ is 2^8 radians.

The recurrent frequency of Δt clock pulses is established by pulse generator 202 in FIG. 11a. This generator produces precisely spaced pulses, 2^{12} per second, which are buffered by logic circuits 203 and 204. Buffer circuits 203 and 204 operate essentially in the same manner as other buffer circuits already described with reference to other pulse signals. Effectively, circuit 204 produces a clock pulse output during the interval the clock counts from T_1 to T_{48} following the occurrence of a pulse

in the output of pulse generator 202. It will be noted that these Δt clock pulses are coincident with the shifted and weighted numbers $\Delta V_{I/A}$ and therefore serve to gate said number.

- 5 The output of serial binary adder 199 is applied to magnetostrictive storage device 201 by coil 205 coupled to the one end thereof and the stored serial binary number is detected by coil 206 coupled to the other end thereof and fed back to serial binary adder 199 via amplifier 207.
- 10 Referring next to increment detector 208 in FIG. 11b there is shown means for detecting and buffering pulses representative of given predetermined increments of latitude λ , serving the same purpose as already briefly described with reference to device 77 in the latitude part of FIG. 6a. Increment detector 208 is responsive to the A and $\bar{A}$ input to serial adder 199 and also to the carry signals denoted C and $\bar{C}$ in the output of said adder as well as a predetermined clock pulse, for example, T_{20} .
- 15 Effectively, increment detector 208 detects any increase in the number λ (whose magnitude is represented by 47 binary bits) beyond the 20th bit. Now it can be shown by reference to the operation of a serial binary adder of the type employed herein that when an incremental 20 number is added to a stored number and at a given instant a binary place of that incremental number is not represented by a binary bit; but when, however, there is a carry pulse produced in the serial binary adder at the given instant, then the stored number has been increased 25 by a given predetermined amount. Furthermore, if at the given instant the binary place is represented by a binary bit and at the same instant, no carry is indicated in the serial binary bit adder then the stored number has been decreased by the same magnitude of said predetermined amount. It is the purpose of dynamic logic circuits 209 and 210, which are responsive to the incremental inputs to serial binary adder 199 and to the carry signals produced therein as well as a given predetermined clock pulse such as T_{20} to detect increments of λ 30 by 2^{-20} times the maximum of value of λ , or 2^{-20} , 2^8 which is 2^{-12} radians. The α outputs of circuits 209 and 210 are fed via diodes 211 and 212, respectively, to one of the inputs of dynamic circuit 213. These outputs are also fed to different inputs of double input bistable flip-flop circuit 214. Consequently, each time stage 214a of flip-flop circuit 214 produces an output, it is indicative 35 that the last predetermined increment of the value λ was negative and each time stage 214b produces an output it is indicative that the last predetermined increment of λ 40 was positive. The output of stage 214a is applied to one input of logic dynamic circuit 215.
- 45 The action of dynamic circuits 213, 215 and 216 is to buffer increment representing pulses from diodes 211 and 212 and to buffer sign signals representing the sign of those increments pulses from stage 214a of the flip-flop circuit. The coordinated action of circuits 213, 215 and 216 is typical of other similar circuits already described with reference to buffer devices 124 and 134 shown in FIGS. 7 and 8, respectively. Briefly, clock pulses are produced in the α output of circuit 215 during the interval 50 that the clock counts from T_1 to T_{48} following the occurrence of a pulse in the output of circuits 209 or 210. These clock pulses appearing in the output of circuit 216 are denoted $\delta_{\Delta\lambda}$ clock pulses. The signal from stage 214a 55 representing the sign of the increment to λ is buffered to produce clock pulses in the output of dynamic circuit 215 in coincidence with the clock pulses in the output of 216.

- 60 It should be noted in reference to FIG. 11a that the outputs of gate 180 consist of the shifted and filled in numbers δR_{ij} and $\bar{\delta}R_{ij}$ upon the occurrence of associated v_j pulses from accelerometer devices. Now as has already been shown with reference to fill-in circuits in FIGS. 10a, 10b and 10c, the shifted and filled in numbers δR_{ij} are each represented by 16 binary places, 15 of said 16 places 65 representing the magnitude of the number and the 16th

representing the sign. Therefore, when such a 16-place number is added to a 48-place number such as V_I stored in magnetostrictive storage device 181 and when the increment δR_{ij} represents a negative amount, there will be 48 minus 16 or 32 fill-in pulses missing. As has already been shown, these fill-in pulses appeared in the η output of gate 180 when the incremental number δR_{ij} appearing in that output represents a negative increment or in the α output of gate 180 when the δR_{ij} number represents a positive increment. It is a purpose of dynamic circuits 217 and 218 to add the 32 extra fill-in pulses to the α and η output of gate 180, respectively, as is required to properly fill in incremental numbers represented by that output for subsequent addition to the 48-bit number V_I stored in magnetostrictive device 181. As can be seen with reference to circuits 217 and 218, if a pulse appears in the α or η output of gate 180 in time coincidence with clock pulse T_{18} which is at the end of the 16-bit number representing δR_{ij} , circuits 217 and 218 will continue to add pulses to the α and η outputs, respectively, of gate 180 until the subsequent T_{48} clock pulse occurs. Consequently, the necessary fill-in pulses will be added to the α and η output of gate 180 whenever required.

Turning next to FIGS. 12a and 12b there is shown dynamic logic circuits identical to those shown in FIGS. 11a and 11b. FIGS. 12a and 12b show details of the longitude part of the generalized system already described with reference to FIG. 6a. Since the circuitry in FIGS. 12a and 12b is identical to that already described with reference to FIGS. 11a and 11b and differs only in that the inputs and outputs are different, a detailed description of the operation of this circuitry will not be included. It is sufficient to say that gate 219 in FIG. 12a is identical in construction and operation to gate 180 in FIG. 11a; however, gate 219 serves to gate shifted and filled-in numbers δR_{IIj} rather than δR_{ij} as does gate 180. Furthermore, the output of gate 219 applies increments to a register storing the number V_{II} in magnetostrictive storage device 229 and a weighted and filled-in increment of V_{II} is gated by gating device 221 controlled by $\delta_{\Delta\theta}$ clock pulses and associated sign clock pulses $\sigma_{\Delta\theta}$ and $\bar{\sigma}_{\Delta\theta}$. Furthermore, the weighted filled-in and gated numbers δV_{II} and $\delta \bar{V}_{II}$ are added to the 48-bit serial number $V_{II/A} \cos \lambda$ stored in magnetostrictive storage device 222, the addition being accomplished by the action of serial binary adder 223. A weighted value of the number $V_{II/A} \cos \lambda$ is detected by a coil and applied to an amplifier which in turn feeds fill-in and gating circuit 224 of FIG. 12b, circuit 224 being gated by Δt clock pulses. In FIG. 12b the output of circuit 224 is applied to serial binary adder 225 where said output is added to the 48-bit serial binary number L stored in magnetostrictive storage device 226. Predetermined increments of the value L stored in device 226 are detected and buffered by increment detection circuit 227 which produces $\delta_{\Delta L}$ clock pulses and associated sign clock pulses $\sigma_{\Delta L}$ and $\bar{\sigma}_{\Delta L}$. Returning again to FIG. 12a circuits 228 and 229 serve to add the additional fill-in pulses in the output of gate 219 in the same manner that circuits 217 and 218 add the necessary fill-in pulses in the output of gate 180. Obviously, circuits 219 through 229 are identical to 180, 181, 190, 192, 189, 197, 199, 201, 203, 217 and 218.

Turning next to FIG. 13 there is shown the details including magnetostrictive type storage devices, serial binary adders and dynamic logic circuits for storing serial binary numbers representative of V_{III} , A , and producing buffered pulses representing given predetermined increments of A , denoted herein as $\delta_{\Delta A}$ clock pulses with associated sign clock pulses denoted $\sigma_{\Delta A}$ and $\bar{\sigma}_{\Delta A}$. FIG. 13 shows detailed circuitry for accomplishing what is functionally described in the altitude part of FIG. 6a and, as shown, this includes multiple input gate 230, magnetostrictive storage device 231 for storing the number V_{III} , dynamic gate 232 for feeding increments of V_{III} to serial

binary adder 234 at the repetition rate of Δt clock pulses. Adder 234 serves to add said increments to the number A stored in magnetostrictive storage device 233 thereby effectively integrating V_{III} in real time to obtain the quantity A . Given predetermined increments of the value A stored in magnetostrictive storage device 233 are determined by increment detector 235 and buffered therein to produce the $\delta_{\Delta A}$ clock pulses and associated sign clock pulses. Circuits 230 to 235 are identical in operation to circuits 180, 181, 188 and 190, 192, 189 and 208, respectively, which have been described with reference to FIGS. 11a and 11b. Dynamic logic circuits 236 and 237 shown in FIG. 13 are identical in operation and perform the same functions as circuits 217 and 218 shown in FIG. 11a.

There is one slight difference between dynamic gate circuit 236 in FIG. 13 and dynamic gate circuit 180 in FIG. 11a. The first difference obviously is that circuit 236 responses to shifted and filled in numbers δR_{IIIj} whereas circuit 180 of FIG. 11a responses to shifted and filled in numbers δR_{ij} . Secondly, the input of circuit 236 consists not just of six input "and" circuits, but of seven input "and" circuits, the seventh such "and" circuit is for adding increments of velocity due to gravitation acceleration. It will be shown later that the matrix computer partially described in detail with reference to FIGS. 10a, 10b and 10c is also responsive to pulses representing increments of rotation of the reference frame axes I, II and III. Furthermore, these rotations are such that the reference frame axes are at all times maintained in the direction of longitude, latitude and altitude denoted herein as L , λ and A . Consequently, gravity is at all times in the direction of the coordinate A and as A represents the distance of body 1 from the center of the earth.

Now it can be shown as an approximation, that by adding the sequential clock pulses T_2 and T_3 to the second and thiry binary bits representing the number V_{III} stored in magnetostrictive device 231 each time T_g clock pulses occur (see waveforms of FIG. 18) that the number V_{III} will be altered as it is required to account for gravitational acceleration. Very briefly, gravity is 32.2 feet per second which equals approximately 2^5 feet per second squared. Now since T_g occurs $192/10^6$ times per second then the quantity 2^5 will be added to the value V_{III} every second if a serial binary number having a real value of $2^5 \cdot (10^6/192)^{-1}$ is added to V_{III} at the current rate of T_g clock pulses. Performing this multiplication and division

$$2^5 \cdot (10^6/192)^{-1} = 1.5(2^{-8}) \text{ or } (2^{-8} + \frac{1}{2} \text{ of } 2^{-8})$$

Now it can be shown that the quantity 2^{-8} feet per second on the same scale as the number V_{III} , represented by 47 binary bits circulating in magnetostrictive storage device 231, is represented by the third binary place of the number V_{III} . It is therefore apparent that one half times 2^{-8} is represented by the second binary place of said number and the sum of these two values can be represented by a T_2 pulse followed by a T_3 pulse during the interval of T_g clock pulses.

The maximum value of A represented by the 48-bit number stored in magnetostrictive storage device 233 is 2^{36} feet. This is apparent because A is the time integration of V_{III} and the maximum value of V_{III} is 2^{36} ft./sec. Furthermore, in the process of integrating, V_{III} is weighted by 2^{-12} and integrated with Δt interval pulses representing 2^{-12} seconds.

Turning next to FIG. 14 there is shown dynamic logic circuits and magnetostrictive storage devices operating essentially as described by the functional diagram of the resolver shown in FIG. 6b. As already stated with reference to FIG. 6b, the purpose of the resolver is to compute $\sin \lambda$ and $\cos \lambda$ in response to inputs representing increments of the value λ . FIG. 14 also includes a magnetostrictive storage device for storing the value $A \cos \lambda$ and producing a weighted value denoted $\Delta A \cos \lambda$. As shown in FIG. 14 $\delta_{\Delta A}$ clock pulses and associated sign

clock pulses control gate 238 which serves to gate a shifted and filled in value of $\cos \lambda$. The output of gate 238 is fed to serial binary adder 239 via suitable delay circuits 240 and this shifted and filled in value of $\cos \lambda$ is added to $\sin \lambda$ which is stored in magnetostrictive storage device 241. Simultaneously, a shifted value of $\sin \lambda$ is fed to fill-in circuit 242 and the shifted and filled in output from circuit 242 is gated by gate 243 which is also controlled by $\delta_{\Delta\lambda}$ clock pulses and associated sign clock pulses. The output of gate 243 is fed to adder 244 via suitable delay circuits 245, the function of adder 244 being to add the shifted and filled in value of $\sin \lambda$ to $\cos \lambda$ which is stored in the magnetostrictive device 246, upon the occurrence of a $\delta_{\Delta\lambda}$ pulse. A shifted value of $\cos \lambda$ is fed to fill-in circuit 247 whose output is gated by gate 238 thus completing a loop. Obviously, the action of circuits 238 to 247 is to compute the Equations R and S already described above. It should be noted that $\cos \lambda \cdot \delta_{\Delta\lambda}$ in Equation R is represented by the output of gate 238 just as the output of gate 243 as applied to adder 244 represents $-\sin \lambda \cdot \delta_{\Delta\lambda}$ in Equation S. It should be noted that the output of gate 243 must represent the negative of $\sin \lambda \cdot \delta_{\Delta\lambda}$. Consequently, the shifted and filled in values of $\sin \lambda$ and $\sin \lambda$ fed from fill-in circuit 242 to gate 243 must be applied to the proper "and" input of gate 243. As shown in the figure, $\sin \lambda$ is applied to the same "and" input as $\delta_{\Delta\lambda}$ and $\sigma_{\Delta\lambda}$ and $\sin \lambda$ is applied to the same "and" input as $\delta_{\Delta\lambda}$ and $\sigma_{\Delta\lambda}$ of gate 243.

The output $\cos \lambda$ and $\cos \lambda$ from storage device 246 is fed to gate 248. Gate 248 is controlled by $\delta_{\Delta\lambda}$ clock pulses and associated sign clock pulses thereby serving the same function as add device 86 shown in FIG. 6b. It should be noted that $\cos \lambda$ and $\cos \lambda$ fed to gate 248 are not shifted and therefore do not require fill-in pulses. The output of gate 247 is fed to serial-binary adder 249 via delay circuits 250. The purpose of adder 249 is to add $\cos \lambda$ to the value $A \cos \lambda$ stored in magnetostrictive storage device 251 upon the occurrence of each $\delta_{\Delta\lambda}$ pulse. A shifted value of $A \cos \lambda$ denoted as $\Delta A \cos \lambda$ is obtained from amplifier 252 which is fed pulses from coil 253. Storage device 251 and coil 253 acting in conjunction with amplifier 252 perform the same functions as devices 85 and 87 in FIG. 6b.

As already stated with reference to FIG. 13, each $\delta_{\Delta\lambda}$ pulse represents an increment of A of 2^6 feet. Therefore, if the maximum value of $\cos \lambda$ is unity and was represented by 47 bits stored in magnetostrictive storage device 245 then the maximum binary number of 47 bits, added to the number in storage device 250, would represent 2^6 feet. Consequently, the maximum real value of the 47-bit number in storage device 251 would be only 2^6 feet and this is undesirable. It is desirable that the maximum value of $A \cos \lambda$ stored in device 251 be the same as the maximum value of A stored in device 233 of FIG. 13 and this value is 2^{36} feet. Therefore, it is necessary that the maximum increment added to $A \cos \lambda$ in device 250 represent 2^6 feet and consist of 17 binary bits. As a result, the maximum value of $\cos \lambda$ in device 245 must be represented therein by only 17 binary bits rather than the full 47. This requirement also applies to device 241 because devices 241 and 246 must be identical.

Turning next to FIG. 15 there is shown details including dynamic logic circuits and magnetostrictive storage devices for computing functions already described with reference to the ϕ computer and θ computer in FIG. 6b. Details of the ϕ computer shown in FIG. 15 include gate 254 controlled by $\delta_{\Delta\phi}$ clock pulses and associated sign clock pulses. The purpose of gate 254 is to gate a shifted value of A obtained from device 233 of FIG. 13. This shifted value of A from FIG. 13 must be filled in with T_w' and $\bar{T}_w'$ fill-in pulses. A fill-in circuit for accomplishing this is not shown, however, it would operate in an identical manner to other fill-in logic circuits already

described. The shifted, filled-in and gated output from gate 254 is applied to serial-binary adder 255 via suitable delay circuits 256. The purpose of adder 255 is to add the shifted filled in and gated value of A to the quantity $A \cdot \phi$ stored in magnetostrictive storage device 257, thereby performing the functions of devices 82 and 81 of FIG. 6b. The quantity $A \cdot \phi$ is also fed to serial-binary adder 258 along with the output of unity storage device 259. It should be noted that the assertive and negative values of $A \cdot \phi$ and the assertive and negative values of unity are fed to adder 258 in such a manner that the adder functions as a subtractor. Since $A \cdot \phi$ and unity is always positive, the output of adder 257 represents the difference between $A \cdot \phi$ and unity. This difference is fed to adder 260 which serves to add the difference to the value ϕ stored in device 261, thereby performing the functions of 81 and 83, 84, 57 and 59 of FIG. 6b. The assertive and negative values of ϕ fed to adder 260 and the carry signals generated in adder 260 are applied to $\delta_{\Delta\phi}$ increment detection circuit 262. Circuit 262 is identical in construction and operation to circuits 298, 227 and 235 of FIGS. 11b, 12b and 13, respectively. Consequently, a detailed description of the operation of circuit 261 is not included. The output of circuit 261 consists of $\delta_{\Delta\phi}$ clock pulses and $\sigma_{\Delta\phi}$ and $\bar{\sigma}_{\Delta\phi}$ clock pulses all of which are applied to gate 253 thereby controlling said gate. As already stated above with reference to FIG. 11a it is desirable that $\delta_{\Delta\phi}$ clock pulses present increments of ϕ of $2^{-40} 1./\text{feet}$. Since the shifted and filled in value of A fed to gate 254 consists of a maximum number of 35 bits representing a maximum real value of 2^{-36} feet, each increment added to $A \cdot \phi$ by the action of adder 255 must consist of 35 bits representing a value of $2^{36} \cdot 2^{-40}$ or 2^{-4} . Now if each 35-bit increment added to the value $A \cdot \phi$ in device 257 represents a real value of 2^{-4} , then the maximum value of $A \cdot \phi$ represented by 47 bits stored in device 257 must represent a real value of 2^8 . Also the maximum value of unity register 259 represented by 47 bits must be 2^8 . The maximum value of ϕ represented by 47 bits stored in device 261 may be varied considerably without appreciably altering the efficiency of the ϕ computer. However, it is desirable for reasons that will not be described herein that the maximum value of ϕ represented by 47 bits in device 261 be close to maximum value of $A \cdot \phi$ represented by 47 binary bits in device 256. For this reason, the maximum value of ϕ represented by 47 binary bits in device 261 will be representative of the real value of $2^5 1./\text{feet}$. Consequently, if each $\delta_{\Delta\phi}$ pulse from circuit 261 is to represent $2^{-40} 1./\text{feet}$ and increment detector 262 must also respond to a T_2 clock pulse so that the action of adder 260 upon receiving the second binary bit of the number ϕ is examined.

Turning next to the detailed representation of the θ computer shown in FIG. 15, there is shown circuitry identical in construction and operation to the ϕ computer of FIG. 15. The θ computer consists of gate 263 for gating shifted and filled in values of $A \cos \lambda$ in response to $\delta_{\Delta\theta}$ clock pulses, adder 264 responsive to the value $A \cos \lambda \cdot \theta$ and shifted and filled in gated values of $A \cos \lambda$, magnetostrictive storage device 265 for storing the 47-bit number representing $A \cos \lambda \cdot \theta$, adder 266 which functions as a subtractor, adder 267 for adding the difference between $A \cos \lambda \cdot \theta$ and unity to device 268 which stores a 47-bit number representing θ and increment detector 269 for detecting increments of θ , each increment representing $2^{-40} 1./\text{feet}$. Obviously, devices 263 to 269 are identical to devices 254 to 262, respectively.

Turning next to FIG. 16 there is shown details including dynamic circuits, dynamic logic circuits and magnetostrictive storage devices operating as functionally described with reference to FIG. 6c. The purpose of the system shown in FIG. 16 is to produce δ_I and δ_{III} clock pulses and associated sign clock pulses for controlling the

operation of the matrix computer already described with reference to FIGS. 10a, 10b and 10c. The equations computed by the system functionally described by FIG. 6c and described in detail by FIG. 16 are equations T. The rotation angle of the reference frame axis I is represented by 47-bit number stored in magnetostrictive storage device 270. This number is formed by increments added thereto representing $\Delta L \cos \lambda$ and $\Omega \Delta t \cos \lambda$, the increments being added by the action of adder 271. The proper form of these increments are produced in the output of gate 272 which is coupled via suitable delay circuits 273 to the input of adder 271. Gate 272 consists of 4 input "and" circuits, the first two of which are for gating an unshifted value of $\cos \lambda$ with $\delta_{\Delta L}$ clock pulses and the second two "and" gates are for gating an unshifted value of $\cos \lambda$ with $\Omega \Delta t$ clock pulses which are obtained from the clock and which will be described with reference to FIG. 18. The logic performed by gate 272 is apparent and will not be described in detail.

The maximum value of the 47-bit numbers stored in device 270 is determined in the following manner; each $\delta_{\Delta L}$ pulse represents an increment of L of 2^{-12} radians. This fact has already been established with reference to increment detection circuit 227 of FIG. 12b. Furthermore, the maximum value of $\cos \lambda$ represented by 47-binary bits is 2^{30} and, therefore, the maximum increment added to the number in device 270 by the action of adder 271 is $2^{-12} \cdot 2^{34} \cdot 2^{18}$ and is represented by 47 binary bits. Consequently, the maximum value of a number in device 270 represented by 47 binary bits is 2^{18} radians. Now as already stated and as will be shown subsequently in further discussion of the matrix computer in FIGS. 10a, 10b and 10c, it is desirable that each δ_I pulse represent an increment of rotation to 2^{-6} radians. Therefore, if the 19th binary bit of the 47th bit number stored in device 270 is examined by increment detection circuit 274 then the δ_I clock pulses and associated sign clock pulses produced in the output circuit 274 will represent increments of rotation of the reference frame around the I axis of 2^{-6} radians.

The details of the δ_{III} computer shown in FIG. 16 are identical in construction and operation to the details of the δ_I computer just described. The δ_{III} computer consists of a gate 275 for gating $\sin \lambda$ in accordance with $\delta_{\Delta L}$ pulses and $\Omega \Delta t$ pulses, and add circuit 276 for adding the output of gate 275 to the 47-bit number stored in device 277, representing the rotation angle of the III reference axis and increment detection circuit 278 for detecting increments of said angle of 2^{-6} radians. Devices 275 through 278 are identical in construction and operation to devices 272, 271, 270 and 274, respectively. The only difference between these circuits is that gate 275 serves to gate $\sin \lambda$ whereas gate 272 serves to gate $\cos \lambda$.

It is obvious from FIG. 5 that δ_{II} is equivalent to δ_{AX} . Therefore, the magnetostrictive storage 201 in FIG. 11b which stores the value λ can readily be employed in conjunction with an increment detection circuit to produce δ_I , σ_I and $\bar{\sigma}_I$ clock pulses in the same manner that increment detection circuits 274 and 278 produce δ_I and δ_{III} clock pulses, respectively. Now since the maximum value of λ stored in device 201 of FIG. 11b is 2^8 radians and is represented by 47 binary bits, an increment detection circuit coupled to adder 199 which feeds device 201 and fed T_{33} clock pulses to thereby examine the 33rd bit in the 47-bit number representing λ will yield δ_I pulses each representative of an increment of rotation of the reference frame about the I axis of 2^{-6} radians. An increment detection circuit for accomplishing this is not shown but would operate in an identical manner to the increment detection circuit 208 shown in FIG. 11b except that it would respond to T_{33} clock pulses rather than T_{20} clock pulses as does circuit 208.

Returning again to FIGS. 10a, 10b and 10c, the description of the operation of gates 174 and 175 will now be continued. As already described with reference to

FIG. 10a, gate 174 feeds shifted and filled in values of R_{Iz} to adder 177 wherein these values are added to the numbers R_{Ix} , R_{IIX} and R_{IIIIX} stored in device 152 in response to each δ_I clock pulse. At the same time gate 174 serves to feed shifted filled in values of R_{Iy} to adder 176 where these values are added to the numbers R_{Ix} , R_{IIX} and R_{IIIIX} when δ_I clock pulses occur. Furthermore, these additions are made only during the interval of T_a clock pulses shown in waveform diagrams of FIG. 18. The interval of T_a clock pulses commences at T_1 and continues up to T_{48} . As shown in waveforms of FIG. 18 T_b clock pulses occur immediately after T_a and occur for a count of 16. Consequently, T_b clock pulses occur during the interval the clock counts from T_{48} to T_{64} . Likewise, in the same manner T_c and T_d pulses follow T_d each including a different interval of 16 clock pulses and at the end of interval T_d , T_a commences again for a count of 48.

It is obvious from FIG. 18 that during the interval of T_a clock pulses, alterations to the numbers in device 152 are made to account for rotations of body 1 about its x axis. The action of gates 174 and 175 during the intervals T_b , T_c and T_d is to feed increments to adders 177 and 176 to alter the numbers R_{Ix} , R_{IIX} and R_{IIIIX} as required to account for rotations of the reference frame axes as set forth in the first three of Equations N. During the interval of T_b when the number R_{Ix} is feeding through adders 177 and 176, shifted and filled in values of the numbers R_{IIX} and R_{IIIIX} obtained from fill-in circuits 166 and 167, respectively, are fed through gates 175 and 174, respectively, in response to δ_{II} and δ_{III} clock pulses, respectively. In this manner the first of Equation N is computed, likewise and in the same manner during the interval of T_c clock pulses the second of Equation N is computed and during the interval of T_d clock pulses the third of Equations N is computed.

Turning to FIGS. 10b and 10c there is shown in each of these drawings, gates similar to gates 174 and 175 operating in essentially the same manner. The action of these gates in FIG. 10b is to compute the fourth, fifth and sixth of Equations N and the action of the two gates shown in FIG. 10c is to compute Equations 7, 8 and 9 of Equations N. Consequently, the nine numbers denoted generally as R_{ij} stored in devices 152, 153 and 154 are altered in response to reference frame rotation pulses δ_I , δ_{II} and δ_{III} thereby maintaining the reference frame axis at all times in the directions of latitude, longitude and gravity.

It should be noted that no buffer circuits have been described for buffering δ_I , δ_{II} and δ_{III} pulses to produce the corresponding clock pulses and corresponding sign clock pulses. The three buffer circuits required for this are identical in construction and operation. Consequently, only the buffer circuit included in increment detection circuit 274 for buffering δ_I pulses is described below with reference to FIG. 17. In FIG. 17 there is shown increment detector 274 coupled to adder 271 and responsive to T_{17} pulses. Logic circuits 279, 280 and diodes 281 and 282 and flip-flop circuit 283 operate at their counterparts of the increment detector 208 shown in FIG. 11b and is described with reference to FIG. 11b. In addition there are three other dynamic logic circuits 284, 285 and 286 operating in exactly the same manner as dynamic logic circuits 146, 147 and 148 shown in the buffer circuit of FIG. 7. The only difference between these three dynamic logic circuits and those in FIG. 7 are that clock pulse inputs are different. It is necessary that the clock pulse inputs be different because δ_I pulses must be buffered to yield clock pulses during the interval the clock counts from 48 to 96 wherein δ_I pulses must be buffered to yield clock pulses during the interval the clock counts from 1 to 48. This is shown by waveforms in FIG. 18.

Turning next to FIG. 20b there is shown a section of the electronic clock for producing the interval signals T_{ix} , T_{iy} , T_{iz} , T_g and R pulses employed in certain of the buffers. As shown in FIG. 20b the output from stage

300a of flip-flop circuit 300 in FIG. 20a is applied to single input bistable flip-flop circuit 323. Since flip-flop 300 serves to count the number of times ring counter 293 counts to 48 and this count is by two's, then flip-flop 323 serves to count by four's the number of times ring counter 293 counts to 48. Therefore, the output of stage 323b of flip-flop 323 when applied to gates 324, 325, 326 and 327 serves to open these gates every fourth time counter 293 counts 48 and the gates remain open during the interval the counter 293 takes to count 48. In much the same manner, stages 323a of flip-flop 323 controls gates 328, 329 and 330, 331 opening these for every fourth count of 48 incurred by ring counter 293. Obviously, gates 324 to 327 are open while gates 328 to 331 are closed and vice versa. Pulses generated by the system of FIG. 20a for triggering the beginning and end of each of the intervals T_{1x} , T_{1y} and T_{1z} and T_g are $T_{1'}$, $T_{18'}$, $T_{49'}$ and $T_{64'}$. Consequently, these pulses are fed via suitable delays through gates 324, 325, 326 and 327, respectively, and also through gates 328, 329, 330 and 331, respectively, to flip-flop circuits 332, 333, 334 and 335. The output of stage 332a consists of a signal during an interval T_{1x} , the output of stage 333a consists of a signal during the interval T_{1y} , the output of stage 334a consists of a signal during the interval T_{1z} and the output of stage 335a consists of a signal during the interval T_g . These outputs are shown in waveform diagrams of FIG. 18. Since all the other T_1' pulses are R pulses, the output of gate 324 which consists of every other T_1' pulse serves to produce R pulses.

As shown in waveforms of FIG. 19, T_w' pulses consist of 35 clock pulses commencing with T_1 while $T_{w'}$ pulses consist of 13 clock pulses commencing with T_{35} . Furthermore, T_w' pulses repeat each time the clock counts to 48 and so do $T_{w'}$. One simple method of generating T_w' and $T_{w'}$ pulses is shown in FIG. 20c and includes a double input bistable flip-flop circuit 236, one stage responsive to T_1 pulses from counter 293 and the other stage responsive to T_{35} pulses from counter 293. The output of stages 336a of flip-flop 336 controls gate 337 while the output of stage 336b controls gate 339. These gates gate one microsecond block pulses from pulse generator 292 producing T_w' and $T_{w'}$, fill-in pulses.

While we have described in considerable detail the structure and operation of a navigation computer in accordance with one embodiment of our invention, it must be recognized that other rotation and translation sensors could be employed feeding signals to computer circuits in response to aircraft accelerations and rotations, aircraft rotations and translations and that analog techniques as well as parallel digital techniques could be employed for computing equations as set forth in the specification without deviating from the spirit and scope of this invention as set forth in the accompanying claims.

We claim:

1. An inertial navigation system comprising rotation sensors in a body producing pulses representing increments of body rotation in inertial space, said pulses controlling gating devices in a computer for computing and storing body attitude with respect to an imaginary reference frame with a second computer coupled thereto and responsive to inertial sensors in said body for computing and storing body position with respect to said reference frame, said imaginary reference frame axes rotating with the change of the earth latitude, longitude and gravity due to the rotation of the earth and the movement of said body to remain in alignment with said earth latitude, longitude and gravity, detecting means coupled to said position computer for detecting given incremental changes in reference frame attitude with respect to inertial space and producing pulses representative thereof and means for applying said pulses to said gating devices thereby altering said stored body attitude in somewhat the same manner said rotation sensor pulses alter stored body attitude to account for body rotations and reference frame

rotations with respect to inertial space, each of said means being discrete structural elements.

2. An inertial navigation system comprising means responsive to the digital outputs of rotation sensors in a body for computing and storing direction cosines representing body attitude with respect to an imaginary reference frame, with second computing means coupled thereto and responsive to the digital outputs of inertia sensors with respect to said body for computing body position in said reference frame, said imaginary reference frame axes rotating with the change of the earth latitude, longitude and gravity due to the rotation of the earth and the movement of said body to remain in alignment with said earth latitude, longitude and gravity, and means coupled to said second computing means for detecting changes in said stored position and feeding signals representative of said changes to said cosine computing means thereby altering said cosines as required to account for rotations of said reference frame with respect to inertial space, each of said means being discrete structural elements.

3. An inertial navigation system comprising first computing means responsive to the digital outputs of rotation sensors in a body for computing and storing direction cosines representing body attitude with respect to an imaginary reference frame orientated in the directions of gravity, latitude and longitude with second computing means coupled thereto and responsive to the digital outputs of inertia sensors in said body for computing and storing body position in terms of altitude, latitude and longitude, said imaginary reference frame axes rotating with the change of the earth latitude, longitude and gravity due to the rotation of the earth and the movement of said body to remain in alignment with said earth latitude, longitude and gravity, third computing means coupled to said second computing means for computing reference frame rotations with respect to inertial space in terms of said stored altitude, latitude and longitude and means coupled thereto for applying signals representing said reference frame rotations to said first computing means to alter said cosines as required to maintain said reference frame orientation, each of said means being discrete structural elements.

4. An inertial navigation system comprising first computing means responsive to the digital outputs of rotation sensors in a body for computing and storing body attitude with respect to an imaginary reference frame with second computing means coupled to said first computing means and responsive to the digital outputs of inertia sensors in said body for computing and storing body position in terms of altitude, latitude, and longitude, said imaginary reference frame axes rotating with the change of the earth latitude, longitude and gravity due to the rotation of the earth and the movement of said body to remain in alignment with said earth latitude, longitude and gravity, third computing means coupled to said second computing means for computing reference frame rotations with respect to inertial space in terms of said stored altitude, latitude and longitude and means coupled thereto for applying signals representing said reference frame rotations to said first computing means to alter said stored attitude as required to account for reference frame rotations in inertial space, each of said means being discrete structural elements.

5. An inertial navigation system comprising first means for computing and storing direction cosines representing body attitude with respect to an imaginary reference frame responsive to pulses from rotation sensors in a body, said pulses representing increments of rotation of said body with respect to inertial space with second computing means coupled to said first computing means for computing and storing body position in terms in altitude, latitude and longitude, and responsive to the digital outputs of inertia sensors in said body, said imaginary reference frame axes rotating with the change of the earth latitude, longitude and gravity due to the rotation of the

earth and the movement of said body to remain in alignment with said earth latitude, longitude and gravity, third computing means coupled to said second computing means for computing reference frame rotations with respect to inertial space in terms of said stored altitude, latitude and longitude, means coupled to said third computing means for producing pulses representing increments of said reference frame rotation and means for applying said pulses representing incremental reference frame rotations to said first computing means to alter said stored cosines as required to maintain said reference frame orientated in the directions of gravity, latitude and longitude, each of said means being discrete structural elements.

6. A system for computing and storing the position of a body in terms of altitude, latitude and longitude comprising translation and rotation sensors fixed to said body, first computing means responsive to the digital outputs of said rotation sensors for computing and storing the attitude of said body with respect to an imaginary reference frame having its axes aligned with gravity, latitude and longitude, second computing means responsive to said stored attitude and to the digital outputs of said translation sensors for computing and storing the velocity of said body in said reference frame, said imaginary reference frame axes rotating with the change of the earth latitude, longitude and gravity due to the rotation of the earth and the movement of said body to remain in alignment with said earth latitude, longitude and gravity, integration means responsive to said stored velocity for computing and storing said altitude, latitude and longitude, means coupled to said integration means for computing and storing angular rotations of said reference frame axes with respect to inertial space with means coupled thereto for detecting predetermined incremental changes in said stored angular rotations and producing pulses representative thereof and means for applying said pulses to said first computer means to alter said stored attitude as required to maintain said reference frame axes aligned, each of said means being discrete structural elements.

7. A system providing information representing the position of a body with respect to an imaginary reference frame comprising translation and rotation sensors fixed to said body and having digital outputs from said translation and rotation sensors, first computing means responsive to said rotation sensors for computing and storing direction cosines representing the attitude of said body with respect to said reference frame, second computing means responsive to said stored cosines and said translation sensors for computing and storing the velocity of said body with respect to said reference frame, said imaginary reference frame axes rotating with the change of the earth latitude, longitude and gravity due to the rotation of the earth and the movement of said body to remain in alignment with said earth latitude, longitude and gravity, integration means responsive to said stored velocity for computing and storing the position of said body and said reference frame, means coupled to said integration means for computing reference frame rotation angles in terms of said stored position with means coupled thereto for detecting incremental changes in said stored angles and producing signals representative thereof and means coupling said signals to said first computer means for altering said stored cosines as required to account for reference frame rotations in inertial space, each of said means being discrete structural elements.

8. A system providing information representing the position of a body with respect to an imaginary reference frame comprising translation and rotation sensors fixed to said body producing pulses representing increments of body translation and increments of body rotation in the direction of body axes with respect to inertial space, first computing means having gating means responsive to said rotation pulses for computing and storing direction cosines representing the angles between said body axes and the axes of said reference frame, second computing means

coupled to said first computing means and responsive to said stored cosines and said translation pulses for computing and storing the velocities of said body in the directions of said reference frame axes, said imaginary reference frame axes rotating with the change of the earth latitude, longitude and gravity due to the rotation of the earth and the movement of said body to remain in alignment with said earth latitude, longitude and gravity, integrating means coupled to said second computing means for computing and storing the position of said body with respect to said reference frame, means coupled to said integrating means for computing and storing the angular rotation of said reference frame axes with respect to inertial space with detecting means coupled thereto for detecting predetermined increments of said stored angular rotation producing pulses representative thereof and means for applying said pulses to said gating means to alter said direction cosines in essentially the same manner as said direction cosines are altered by pulses from said rotation sensors thereby accounting for body rotations and reference frame rotations with respect to inertial space, each of said means being discrete structural elements.

9. An inertial navigation system for computing body position in terms of altitude, latitude and longitude comprising translation and rotation sensors fixed to said body producing pulses representing incremental changes in body velocity and rotation angle in the direction of body axes with respect to inertial space and producing translation and rotation pulses representative thereof, first computing means responsive to said rotation pulses for computing and storing numbers representing the orientation of body axes with respect to an imaginary reference frame axes, second computing means coupled to said first computing means and responsive to said stored numbers and said translation pulses for computing and storing velocities of said body with respect to the direction of said reference frame axes, said imaginary reference frame axes rotating with the change of the earth latitude, longitude and gravity due to the rotation of the earth and the movement of said body to remain in alignment with said earth latitude, longitude and gravity, means for storing body position in terms of altitude, latitude and longitude with means coupled thereto for computing the sine and cosine of latitude, means for multiplying said stored altitude by said stored cosine of latitude and storing the product, first dividing means for dividing one of said stored velocities by said stored altitude and second dividing means for dividing another of said stored velocities by said stored product of altitude times the cosine of latitude, integration means coupled to said first and second dividing means and another of said stored velocities for computing said altitude, latitude and longitude, means coupling the output of said integrating means to said altitude, latitude and longitude storage means, fourth computing means responsive to said stored longitude, said stored sine of latitude and said stored cosine of latitude for computing and storing the rotation angles of said reference frame axes required to maintain said reference frame axes in line with gravity, latitude and longitude, with detection means coupled thereto for detecting predetermined increments of said stored angles and producing pulses representative thereof and means coupling said pulses to said first computer means to alter said stored direction cosines as required to account for reference frame rotations with respect to inertial space maintaining the reference frame axes at all times in the directions of gravity, latitude and longitude, each of said means being discrete structural elements.

10. A system for computing and storing numbers representing the altitude, latitude and longitude of a body comprising translation and rotation sensors fixed to said body for producing translation and rotation pulses, each translation pulse representing a given predetermined increment of body velocity in the direction of a body axes and each rotation pulse representing a predetermined

increment of angular rotation of said body about a body axes, means for storing direction cosines representing angles between said body axes and the axes of an imaginary reference frame, first gating means coupling weighted values of certain of said stored direction cosines to adding means coupled to the input of others of said stored direction cosines, said gating means being controlled by said rotation pulses, means for storing numbers representing the velocities of said body with respect to the directions of said reference frame axes, said imaginary reference frame axes rotating with the change of the earth latitude, longitude and gravity due to the rotation of the earth and the movement of said body to remain in alignment with said earth latitude, longitude and gravity, second gating means coupling weighted values of various of said stored direction cosines to add means coupled to the inputs of said means for storing said velocities, said second gating means being controlled by said translation pulses, means for storing numbers representing said altitude, latitude and longitude with means coupled thereto for computing and storing cosine of latitude and sine of latitude, first dividing means for dividing one of said stored velocities by said stored altitude, second dividing means for dividing another of said stored velocities by said stored altitude and said stored cosine of latitude, means for integrating said stored altitude, the output of said first divider and the output of said second divider, the output of said integrating means being coupled to the input of said means for storing altitude, 20
